UNITED STATES PATENT OFFICE.

JOHN E. OSTLINE, OF LIVERPOOL, ENGLAND, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed December 12, 1924, Serial No. 755,374, and in Great Britain January 1, 1924. Renewed March 28, 1929.

The present invention concerns improvements in or relating to the extension of automatic telephone systems to large networks which are originally purely manual, but at the same time it should be understood that certain of the features are applicable to telephone systems generally. More particularly the invention relates to telephone systems employing register senders and the principal object of the present invention is to provide a system which will enable a conversion of large networks from manual to automatic working to be effected in a most economical manner consistent with meeting all the requirements of the transition stages and the ultimate conditions.

A principal feature of the present invention is the arrangement whereby loop impulses generated by the register sender alone can control the operation of automatic switches. This avoids the use of repeaters between exchanges interconnected by direct trunk lines and enables the construction of the repeaters required to be considerably simplified, consequently a further feature of the present invention is the provision of special repeaters to meet these conditions.

Further in order that the calling party cannot control the switches under any conditions while at the same time enabling the metering arrangements to be simplified, battery feed for the calling party is fed from the first selector. Other features of the invention include means for preventing impulses being generated whenever a secondary non-numerical switch is seized until the next numerical switch is seized and also for enabling a register sender to exert a different controlling effect according to the route over which it is seized, both these features being conveniently effected by a polarized relay responsive to a reversal of current over the talking or impulsive conductors.

Another feature of the invention concerns a register sender adapted to be readily modified so as to enable the register switch to be used either in a three or two digit system, that is a system employing either two or three digits for selecting the required exchange.

Another feature of the present invention concerns improved arrangements for transmitting a distinctive tone to the calling party

should he delay to dial after removing his receiver or after dialling an incomplete number.

55

Still another feature of the present invention concerns an improved impulsing circuit in which two impulsing relays in different switches are arranged to be controlled over a calling party's loop circuit, in such manner that both relays may energize in series with the calling party's loop during the setting up of a connection or one may be deenergized by short circuiting it at the switch with which the other relay is associated.

65

These and further features not specifically mentioned above, but set forth in the accompanying claims, will be understood by referring to the accompanying drawings comprising Figures 1 to 12 inclusive, in which:— 70

Fig. 1 is a trunking layout of the system which is shown in detail in Figs. 2 to 12, inclusive.

Figs. 2 to 12, inclusive, are circuit diagrams of sufficient of the apparatus used in a complete director system to illustrate the preferred form of the invention.

75

The line of the automatic substation A, Fig. 2, terminates at the exchange in the line switch LS. The line switch LS has access 80 to a number of trunk relay groups such as TR, each of which is individual to an exchange selector such as ES. There is a secondary line switch associated with each trunk relay group and the secondary switch SLS 85 has access to a number of director selectors DS, Fig. 3, which in turn have access to a number of directors, one of which is shown in Figs. 4-6, inclusive. The line switch LS, Fig. 2 is mechanically of the well known rotary type having however, improved and novel arrangements for restoring its wipers to normal or home position and an improved and novel metering circuit.

90

The line switches LS¹, LS², LS³, LS⁴, and LS⁵ are similar to the line switch LS. The secondary switches SLS, SLS¹ and SLS² are also similar to the line switch LS except that their controlling relays are located in the trunk relay groups and are adapted to control other circuits. The secondary switch SLS³ is mechanically of the well known rotary type in which the wipers have no normal position and move in a forward direction only.

100

- The exchange selector ES is a two motion vertical and rotary switch mechanically of the well known type and has its bank contacts arranged in horizontal rows or levels.
- 5 The exchange selectors ES¹-ES⁴, inclusive, the exchange selector CES, the selectors S-S⁶, inclusive, and the connectors FS'-FS³, inclusive, are of the same type of switch mechanically.
- 10 The repeater R' is an impulse and busy flash repeater of novel type for manual or automatic to automatic inter-exchange working. The repeaters R² and R³ are provided for use in automatic to manual inter-exchange 15 working and are adapted to transmit a special holding current back to hold up switches independently of the calling party. The repeater R is a special repeater for use in connection with calls from an automatic to a 20 manual exchange having a call indicator equipment and in itself forms no part of the present invention.
- 25 The complete director illustrated in Figs. 4-6, inclusive, comprises essentially the master digit switch MDS, the B and C digit register BCR, Fig. 5, the sender control switch SCS and the digit registers DR¹-DR⁴, inclusive, Fig. 6, and the sending switch SEN, Fig. 4.
- 30 The master digit switch MDS, Fig. 5, is mechanically a simple switch having wipers 308 and 309, which are rotated in a forward direction by the stepping magnet 338 and which are restored to normal upon the energization of release magnet 348, whose circuit is controlled through off normal contacts 347. The digit registers DR¹-DR⁴, inclusive, Fig. 6, are similar to the master digit switch MDS.
- 35 The sender control switch SCS, Fig. 6, is mechanically similar to the line switches LS, and to the secondary switch SLS³, and its wipers are moved in a forward direction only by the stepping magnet 387 and are advanced to their normal position by the operation of 40 the same stepping magnet.
- 45 The wipers of the sender control switch SCS are advanced upon the backward stroke of the stepping magnet 387 rather than upon the forward stroke. The sending switch SEN, Fig. 4, is similar to the mechanism of the switch SCS.
- 50 The B and C digit register BCR, Fig. 5, is a two motion vertical and rotary switch similar to the exchange selector ES. The intermediate distributing frame I.D.F., Fig. 5, is individual to the director D.
- 55 A description will first be given of the general layout of Fig. 1, showing diagrammatically automatic exchanges Nos. 1, 2 and 3, with director equipment, A operator's positions, at manual exchanges Nos. 2 and 3, call indicator position at manual exchange No. 1, toll operator's position at the manual exchange No. 4 and a mechanical tandem exchange MTE.

The layout is representative without going into unnecessary complications of all calls which may be set up in a large network having offices of the type described. It will be clear that a number of different kinds of connections may be set up, and therefore, it is proposed in the first place to describe a local connection in the automatic exchange No. 1, which is to be extended from the calling party A to the wanted party A¹. When the calling party A removes his receiver his individual line switch LS will operate to select an idle trunk relay group TR with which it is then associated by means of the secondary line switch SLS to an idle director selector DS. 70

75 The calling party will first operate his calling device to send out three digits corresponding to the first three letters of the name of the automatic exchange No. 1 and then the four digits representing the wanted party's number. 80

85 The director selector DS will respond to the first digit dialled and then automatically select an idle director, such as D. The director D will now respond to the remaining digits dialled and send out a single train of 90 impulses which is determined by the dialling of the first three digits corresponding to the first three letters of the wanted exchange to an exchange selector such as ES and then the digits of the wanted subscriber's number. 95

The exchange selector ES will respond to the first series of impulses sent out by the director and then automatically select an idle trunk to a first selector such as S. The director will now send out the four series of impulses corresponding to the wanted party's number. 100

The selector S will respond to the first series and then automatically hunt for an idle second selector such as S¹ which responds to the second series of impulses and hunts 105 for an idle final selector or connector, such as FS which responds to the last two series of impulses to establish connection with the line of substation A¹.

110 A connection from the subscriber A in the automatic exchange No. 1, to the subscriber at the substation A³ in the automatic exchange No. 3 is set up in substantially the same manner by the director. The calling subscriber A will first dial the three digits representing 115 the first three letters of the name of automatic exchange No. 3 and then four digits representing the number of the subscriber at substation A³. The first three digits recorded in the director D will now, however, be 120 translated into a three digit office code and the first series of impulses sent out by the director D will operate the exchange selector ES¹ as before, the second series of impulses, the exchange selector, such as ES¹ in 125 the automatic exchange No. 2 and the third series of impulses, the exchange selector ES⁴ in the automatic exchange No. 3. It is assumed that an exchange selector will be required at automatic exchange No. 3 because 130

- there is another exchange in the same building, otherwise first numerical selectors in the exchange could be connected to the junction lines direct. The exchange selector ES^1 will 5 respond to the second series of impulses and then automatically select an idle trunk leading to an automatic to automatic repeater R^1 . It will be noted that the second series of impulses is transmitted direct without 10 the intermediary of a repeater over the inter-exchange trunk line between the exchange selectors ES and ES^1 . The third series of impulses sent out by the director will be repeated by the repeater R^1 to operate the exchange selector ES^2 in the wanted exchange 15 and this selector will then automatically hunt for an idle local selector in that exchange, such as selector S^2 . The remaining four series of impulses corresponding to the number of 20 the wanted subscriber at substation A^3 will now be sent out by the director and will operate the selectors S^2 , S^3 and the connector FS^1 to establish connection with the wanted party A^3 . 25 A connection from the subscriber at substation A in the automatic exchange No. 1 to the subscriber A^2 in the automatic exchange No. 2 is set up in a similar manner to the previous connection, except that the director 30 D now sends out only two series of office selecting impulses. The exchange selector ES responds to the first series of impulses and selects an idle trunk line direct to the exchange selector ES^1 in the automatic exchange No. 2. The exchange selector ES^1 responds to the second series of impulses and this time selects a local first selector in the automatic exchange No. 2 such as the selector S^4 , the remaining series of impulses sent out 35 by the director corresponding to the number of the wanted subscriber at substation A^2 and will operate the selectors S^4 and S^5 and connector FS^2 to establish connection with the wanted party at substation A^2 . It will 40 be noted also that in this connection no repeaters are required in the inter-exchange trunk line between the automatic exchange No. 1 and the automatic exchange No. 2. Local connections in the automatic exchanges 45 Nos. 2 and 3 are set up in a similar manner to the local connection between the subscribers at substations A and A^1 in the automatic exchange No. 1. 50 The subscriber at substation A^4 in the automatic exchange No. 2 can set up a toll call via the manual exchange No. 4 by dialling the digit 0 which will set the director selector DS^1 to the tenth level, whereupon special circuit changes are brought about whereby the 55 director D^1 will send out the necessary series of impulses to route the call over the exchange selector ES^3 , secondary line switch SLS^3 exchange selector ES^4 , automatic to manual repeater R^2 , in the automatic exchange No. 3 to 60 the manual exchange No. 4. The subscriber 65 at substation A in the automatic exchange No. 1 can also set up a toll call by dialling the digit 0 and as before the director selector DS will be raised to the tenth level whereupon special circuit changes will also take place 70 to route the call to the manual exchange No. 4. This time however, it will be seen that the exchange selector ES in the automatic exchange No. 1 has direct access to a trunk line leading to the manual exchange No. 4 by way 75 of the repeater R^3 . 75 A connection from the subscriber at substation A in the automatic exchange No. 1 to the manual exchange No. 1 is set up in the following manner: The calling party first dials the 80 name of the wanted exchange followed by the number of the wanted party in that exchange. Responsive to the dialling of the first three digits representing the name of the wanted exchange the director sends out two series of 85 impulses to select a trunk leading to the manual exchange No. 1, the first series operates, an exchange selector such as ES , which then automatically selects a free trunk to a repeater such as R , the repeater R is of special type so 90 arranged that the first series of impulses received by it are repeated to a succeeding selector such as the call indicator exchange selector CES , while subsequent series of impulses are repeated over the coder selector CS 95 to a coder C . Accordingly when the second series of office selecting impulses are sent out by the director, the call indicator exchange selector CES will be operated and then automatically select an idle trunk line to the secondary line switch SLS^4 at the required exchange. It will be understood that the exchanges accessible to the call indicator exchange selector CES are provided with call 100 indicating equipment. During transmission 105 of the second series of impulses to the selector CES the coder selector CS will have selected an idle coder and subsequent digits transmitted by the director will be repeated to the coder C . As soon as all the digits have 110 been sent the secondary line switch SLS^4 is set in operation to select an idle trunk relay set TR^4 . In due course the trunk relay group is connected with the decoder DC and the 115 digits recorded on the storage relays associated with the coder C are sent out in code over the trunk line. When this process is completed the coder is released and reverts to common use and the number transmitted over 120 the trunk line in code having been decoded at the decoder DC is displayed on the lamps L at the operator's position O . The operator then inserts a plug in the jack of the wanted party's line, whereupon the trunk finder TF will be started up to find the trunk relay set, which has been used. When this is found 125 the calling party will be rung and when he answers, the conversation proceeds in the usual manner. A detailed description of the 130 operation of the call indicating apparatus

in the automatic and manual exchanges is given in the specification of British Patent 229,371.

Connections from the manual exchange No. 5 to manual or automatic exchanges are set up by the operator at the mechanical tandem exchange MTE where impulse senders IM are provided which will send ordinary impulses to operate selectors such as ES⁵ for selecting 10 the required exchange and then according as an automatic or manual exchange has been selected will transmit the numerical portion of the wanted number in ordinary impulses or in a special code for operating a call indicator.

A connection from the subscriber at substation A⁶ in the manual exchange No. 2 to the subscriber A' in the automatic exchange No. 1 is set up via the mechanical tandem exchange MTE as follows: The operator at the "A board" in the manual exchange No. 2 will be signalled in the usual manner by the subscriber at A⁶ and on learning his requirements will repeat the wanted subscriber's 25 number to the operator in the mechanical tandem exchange over an order wire. The tandem operator will thereupon give her the number of an idle interexchange junction line, at the same time pressing an assignment 30 key associated with this line, whereupon a trunk finder such as the trunk finder TF' is started to find the line in connection with which the assignment key has been pressed. When this is found the operator is notified by 35 the lighting of a lamp and she may then set up the required number by operating the appropriate keys of her impulse sender IM. The number of the wanted subscriber at substation A' is 8332345 and of this the first three 40 digits 833 will be used for exchange selecting purposes, and will be converted into a single series of six impulses. The transmission of the translated and numerical portion of the wanted number will depend upon whether 45 the operator at the "A" board has plugged into the trunk assigned to her, and assuming she has done so, the first series of impulses will operate the exchange selector ES⁵ which will select an idle trunk leading to the automatic exchange No. 1 the remaining series 50 of impulses corresponding to the number of the wanted party at the substation A' will operate the first selector S, the second selector S¹ and the connector FS to complete the connection.

If the subscriber at substation A⁶ desires to establish a connection with a subscriber at a call indicator exchange for instance the subscriber A' in the manual exchange No. 1 60 the exchange selecting digits after being translated are transmitted in the form of impulses for operating step by step switches of the ordinary type, while the four digits corresponding to the actual subscriber's number 65 are subsequently sent out over the trunk line

by the exchange selector ES⁵ in code, whereby a considerable saving of transmission time may be effected.

A full description of the apparatus and circuit arrangements in the mechanical tandem exchange is given in the specification of British Patent 229,765.

A connection from the subscriber A⁶ in the manual exchange No. 3 to the subscriber A' in the automatic exchange No. 3 is set up over 70 the "A" board in the manual exchange No. 3 "B board" in the automatic exchange No. 3, first selector such as S⁶, second selector S³ and a final selector FS¹. It will be noted that the operators at the "B board" in the 80 automatic exchange only deal with calls for that exchange and therefore the impulse sender is of a much simpler construction than that provided in the mechanical tandem exchange. A detailed description of the apparatus and circuits associated with the "B board" in the automatic exchange No. 3 is given in the specification of British Patent 85 No. 220,405.

It should be noted that while the connections referred to do not exhaust the complete list of possible connections which could apparently be made in the study of Fig. 1 yet these include representative connections of every class of connection which may be set 95 in a very large network and connections such as the connection between manual exchange No. 2 and the manual exchange No. 4 will be made over a more direct route than via mechanical tandem exchange MTE, and automatic exchanges Nos. 2 and 3, so as to include at most one intermediary exchange. In no case has it been found desirable to have a repeater such as R¹ in serial relationship 100 with the repeater such as R² with the layout 105 according to the present invention.

The apparatus having been described more or less in general, a detailed description of the operation will now be given. For this purpose it will be assumed that the subscriber at substation A, Fig. 1 desires to converse 110 with the local subscriber at substation A'. For the purpose of illustration it will be assumed that the number of the subscriber at substation A', as listed in the directory is 115 8332345, the first three digits 833 designating the desired exchange and the remaining four digits 2345 designating the particular substation in that exchange. It is understood that ordinarily the first three digits 833 120 represent the first three letters of an exchange name and are accordingly listed in the directory as letters instead of digits. This, however, has nothing particular to do with the invention and need not be considered 125 further herein.

Local automatic connection.

Referring now to Figs. 2-8, inclusive, when the subscriber at substation A removes his 130

receiver, line relay 6 energizes over line conductors 2 and 3 in series and earths the private normal conductor 4 at armature 16, thereby making the calling line busy to the 5 connector switches having access to it and closing a circuit for switching relay 5 and stepping magnet 7 in series. Line relay 6 also connects test wiper 10 to the junction of relay 5 and stepping magnet 7 at armature 17, and completes the following circuit 10 for stepping magnet 7: earth, armature 16, home position bank contact 10^a, wiper 10, armature 13 and its resting contact, working contact and armature 17, interrupter contacts 14, stepping magnet 7 to battery. Magnet 7 thereupon rotates the wipers 8-12, inclusive, into engagement with the first bank. Assuming that the trunk terminating in the 15 bank contacts with which wipers 8-12, inclusive, are in engagement is idle, switching relay 5 energizes immediately in series with stepping magnet 7 and seizes the trunk.

In the present case it will be assumed that the first trunk is busy, in which case the test 20 wiper 10 is in engagement with an earthed bank contact, and the earth potential extending to the junction of switching relay 5 and stepping magnet 7 short circuits the former and operates the latter and the wipers 8-12, 25 inclusive, are advanced step by step in search of an idle trunk owing to the buzzer like action of stepping magnet 7 which interrupts its own circuit at contacts 14.

When an idle trunk is reached, which 30 trunk it will be assumed is the one comprising conductors 20-23, inclusive, switching relay 5, being no longer short circuited energizes in series with stepping magnet 7. Stepping magnet 7, however, does not energize at this time on account of the high 35 resistance of switching relay 5. Upon energizing switching relay 5 prepares a circuit for the meter M at armature 15, opens the test circuit and prepares the holding circuit 40 at armature 13, and at armatures 18 and 19 disconnects line conductors 2 and 3 from the windings of line relay 6 and earth respectively, and extends them by way of wipers 8 and 12, the bank contacts upon which they 45 are standing, conductors 20 and 23, normally closed contacts controlled by armature 24 to the windings of the line relay 25 of the trunk relay group TR. Line relay 25 thereupon energizes over the calling line and closes at 50 armature 47, the following circuit for line relay 48 of the exchange selector ES: battery, upper winding of relay 48, resting contact and armature 49 of switching relay 53, upper winding of impedance coil G, right 55 hand winding of polarized relay F, lower winding of impedance coil G, working contact and armature 47, normally closed contacts controlled by armature 50 of switching relay 42, normally closed contacts controlled 60 by armature 51 of polarized relay F, arma-

ture 65 and its resting contact to the lower winding of line relay 48 and earth. Relay 48 energizes over this circuit and opens at armature 54 the circuit of the vertical magnet 55 of the exchange selector ES. 70

Line relay 25 in the trunk relay group TR also completes at armature 26 the following circuit for release relay 27: battery resistance 28, armature 26 and its working contact, relay 27 to earth. Relay 27 being provided with a copper sleeve is slightly slow to pull up as well as being slow to fall away and consequently relay 48 of the selector ES being a quick acting relay deenergizes before relay 27. Release relay 27, upon energizing, 75 earths the release trunk conductor 21 at armature 29, thereby completing a holding circuit over the normally closed contacts controlled by armature 57, conductor 21, wiper 10 and armature 13 for relay 5 before the slow line relay 6 has had time to deenergize. Relay 27 at armatures 29 and 30 completes the following circuit for stepping magnet 31 80 of the secondary line switch SLS, Fig. 3: earth, armature 29 and its working contact, conductor 32', home position bank contact and test wiper 36, conductor 36', armature 38 and its resting contact, armature 39 and its resting contact, working contact and armature 30, resting contact and armature 40, conductor 41, interrupter contacts and stepping magnet 31 to battery. Stepping magnet 31 energizes in this circuit and rotates the wipers 33-37, inclusive, into engagement with the first trunk. If this trunk is 85 idle switching relay 42 energizes in series with stepping magnet 31 over the following circuit: earth, armature 75 and its working contact, armature 94 and its resting contact, working contact and armature 32, resting contact and armature 93, winding of switching relay 42, conductor 41, interrupter contacts and stepping magnet 31 to battery, and seizes the trunk. If the first trunk is busy, 90 test wiper 36 will be in engagement with an earthed bank contact, switching relay 42 will be short circuited and magnet 31 will energize and the secondary switch SLS will select an idle trunk in the manner described above 95 for the line switch LS, which trunk is assumed to be the one comprising conductors 43-46, inclusive, and extending to the director selector DS, Fig. 3.

When this idle trunk is reached, switching relay 42 being no longer short circuited energizes in series with stepping magnet 31, opens the test circuit and earths test wiper 36 at armature 38; thereby earthing test conductor 44; prepares the impulsing circuit at armature 24; at armature 57 earths the release 100 trunk conductor 21 independently of armature 29 of release relay 27; at armature 58 prepares a circuit for stepping relay 59 of the exchange selector ES; at armature 60 105 opens a point in the automatic hunting circuit 110 for the line switch LS, which trunk is assumed to be the one comprising conductors 43-46, inclusive, and extending to the director selector DS, Fig. 3.

When this idle trunk is reached, switching relay 42 being no longer short circuited energizes in series with stepping magnet 31, opens the test circuit and earths test wiper 36 at armature 38; thereby earthing test conductor 44; prepares the impulsing circuit at armature 24; at armature 57 earths the release 115 trunk conductor 21 independently of armature 29 of release relay 27; at armature 58 prepares a circuit for stepping relay 59 of the exchange selector ES; at armature 60 120 opens a point in the automatic hunting circuit 125 for the line switch LS, which trunk is assumed to be the one comprising conductors 43-46, inclusive, and extending to the director selector DS, Fig. 3.

cuit used for returning the secondary line switch SLS to normal position; at armature 61 prepares a circuit for supervisory relay 62; and at armature 50 and 56 completes a 5 new loop circuit for line relay 48 of the exchange selector ES. This loop circuit includes the upper winding of relay 48, working contact and armature 49, working contact and armature 56, conductor 34', wiper 34, conductor 45, normally closed contacts controlled by armature 132, resistance r , conductor 46, wiper 35, conductor 35', armature 50 and its working contact, norinally closed contacts controlled by armature 51, armature 65 and 10 its resting contact to the lower winding of relay 48. Nothing happens responsive to the closure of this loop circuit as relay 48 was already energized over the impedance G and right hand winding of relay F. Relay F is a 15 polarized relay of the shunt field type and only attracts its armature when both windings are energized in the same direction for the reason that when only one winding is energized, the magnetic flux is shunted away 20 from the armature by the low reluctance path through the core of the associated coil. In the director selector DS, Fig. 3, the line relay energizes over the following circuit upon the operation of switching relay 42: battery 25 feed on dial tone conductor DT, normally closed 11th step cam springs controlled by spring 102, winding of relay 103, normally closed springs controlled by armature 104, conductor 43, wiper 33, conductor 33', armature 24 and its working contact, conductor 20, wiper 8, working contact and armature 18, conductor 2, over the calling party's loop, conductor 3, armature 19 and its working contact, wiper 12, conductor 23, lower winding 30 of relay 25 of the trunk relay group TR and earth. Relay 103 energizes over this circuit and completes a circuit for slow release relay 105 at armature 106, whereupon relay 105 energizes and prepares the director 35 selector DS for operation by operating its armature 107-109, inclusive.

The director selector is now in readiness to receive the first digit and when the calling party hears the dialling tone which is projected over the previously traced circuit for relay 103 he dials the first digit 8. When the first exchange selecting digit 8 is dialled relay 25 of the trunk relay group TR and 103 of the director selector DS deenergized eight 40 times responsive to the eight interruptions produced in their circuit by the calling device at substation A, and upon each deenergization relay 103 opens the circuit of slow release relay 105 at armature 106, but relay 105 being slow to release maintains its armatures attracted throughout the series of interruptions. Upon each deenergization, relay 103 closes a circuit for the vertical magnet 110 of the director selector DS as follows: from 45 earth by way of armature 111 and its resting

contact, armature 106 and its resting contact, armature 108 and its working contact, slow series relay 112 to the vertical magnet 110 and battery. Responsive to the eight impulses delivered to the vertical magnet 110 at this 50 time the wipers 113-116, inclusive, are raised opposite to the eighth level of bank contacts. Relay 112 is energized in series with the vertical magnet 110 upon the first impulse of current being delivered to the latter and, 55 being slow to release, maintains its armatures 117 and 118 attracted throughout the series of impulses.

Relay 112 upon energizing, opens a point in the circuit of release magnet 119 at armature 118 and at armature 117 completes the following circuit for stepping relay 120: battery, relay 120, off normal springs 121 (closed on the first vertical step) armature 117 and its working contact, to the earthed release 60 trunk conductor 44. Stepping relay 120 completes a locking circuit for itself at armature 122, and at armature 123 prepares a circuit for the rotary magnet 124. It should be mentioned here that the off normal springs 121' 65 break on the second impulse being delivered to the vertical magnet 110 and not on the first. This arrangement is provided to absorb or cancel a false or preliminary impulse by releasing the switch when only one impulse is 70 delivered to the vertical magnet 110. The first level of bank contacts are, of course, not used as no exchange code starts with the digit one. An instant after the vertical movement of the switch is completed, relay 112 releases 75 and completes the circuit of the rotary magnet 124, which advances the wipers 113-116, inclusive, into engagement with the first set of contacts in the eighth level. Assuming the contacts 125-128, inclusive, extending to the 80 register translator equipment shown in Figs. 4 to 6, inclusive, to be idle, then the rotation of the switch will cease and the switching relay 129 will operate.

Returning now to the transmission of the 85 first series of impulses it will be seen that the lower winding of relay 25 is included in the impulsing circuit, and accordingly responds simultaneously with relay 103. Relay 25 does not perform any useful function at this time 90 other than to maintain release relay 27 energized. The object of this impulsing circuit is to save a wiper on the secondary line switch SLS, Fig. 3.

Returning now to the operation of switching relay 129 which performs the following 95 circuit changes: at armature 130 test wiper 115 is connected to the earthed release trunk conductor 44, thus making the test contact 127 and its multiples in the banks of other director selectors busy.

This earth extends over holding conductor 200, resting contact of armature 204 of relay 205, Fig. 4, conductor 206, armature 207 and its resting contact of relay 208 to relay 209 100

and battery. Relay 209 at armature 210 disconnects earth from the upper bank of the sender control switch SCS, Fig. 6, and at the same armature earths the impulse motor 5 starting conductor IMS; at armature 211 disconnects wiper 213 of the sending switch SEN from magnet 214; at armature 215 connects the common time pulse conductor TPC to the two step time relay 216; at armature 217 prepares a locking circuit for relay 216; at armature 218 removes earth from the chain alarm conductor CAC; at armature 219 disconnects earth from conductor 220 and at the same armature also earths the impulse motor starting conductor IMS. The impulse motor, not shown, is now started and drives the interrupter springs 374 which, however have no effect at this time.

Switching relay 129 at armature 104 transfers the impulse circuit from relay 103 of the director selector DS to the impulse relay 300 of the B and C register BCR, Fig. 5, over conductor 131, wiper 114, contact 126, conductor 201 to relay 300 and battery. Relay 300 at 25 armature 301 completes a circuit for slow release relay 302. Relay 302 at armature 503 prepares a circuit for the vertical magnet 304 of the impulse register BCR, Fig. 5, over conductor 305, slow series relay 306, conductor 307, wiper 308 of the master digit switch MDS in first position to the vertical magnet 304 and battery.

Relay 129 at armatures 132 and 133 connects the following loop circuit across the 35 windings of relay 48 of the exchange selector ES, Fig. 2. Battery, upper winding of relay 48, resting contact and armature 49, resting contact and armature 56, conductor 34', wiper 34, conductor 45, working contact and armature 132, conductor 134, wiper 113, contact 125, conductor 202, resting contact and armature 309 of relay 314, Fig. 5, conductor 310, armature 311, and its resting contact, conductor 312, normally closed contacts controlled by armature 313 of relay S, Fig. 6, conductor 315, left hand winding of shunt field relay 316, Fig. 4, conductor 317, normally closed contacts controlled by armature 318 of relay S, conductor 319, armatures 320 and 50 321, in parallel, conductor 203, bank contact 128, Fig. 3, wiper 116, conductor 135, armature 133 and its working contact, conductor 46, wiper 35, conductor 35', armature 50 and its working contact, Fig. 2, normally closed 55 contacts controlled by armature 51, armature 65 and its resting contact, to the lower winding of relay 48 and earth.

Line relay 48 is maintained energized now over the above traced loop circuit extending through the director D.

The dialling of the next digit 3 of the wanted number causes relay 300 of the B and C digit register BCR, Fig. 5, to transmit three impulses over the previously traced impulse 65 circuit to vertical magnet 304 which raises

the wipers 330-335, inclusive, of the register BCR opposite to the third level of bank contacts.

Slow series relay 306 is energized in series with vertical magnet 304 and at armature 70 336 completes a circuit for slow relay 337. At the end of the series of impulses relay 306 releases and breaks the circuit of relay 337, which does not release immediately and an impulse of current is transmitted to magnet 338 of the master digit control switch MDS from earth, armature 336 and its resting contact, armature 339 and its working contact, conductor 340 to stepping magnet 338 and battery. 75

Magnet 338 advances wipers 308, 309 into second position and when the switch MDS leaves its normal position off normal springs 347 prepare a circuit for release magnet 348. Relay 306 also disconnects earth from the 85 locking circuit of the two step time relay 216 which is previously energized to close its contacts 221 over the time pulse conductor TPC is deenergized, when earth is removed from conductor TPC by the timing device 90 (not shown).

The two-step relay 216 is provided for disconnecting the director in case the calling party should fail to dial the complete number, and in the ordinary operation of the 95 system this relay is not fully operated.

The dialling of the next digit 3 causes relay 300 to transmit three impulses over wiper 308 of switch MDS in second position, conductor 341 to the rotary magnet 342 100 of the impulse register BCR.

The normal post springs NPS are provided for use in 2 digit code systems only. In 3 digit code systems the rotary magnet 342 is wired direct to the second contact in the 105 bank of wiper 308 of the switch MDS.

During the rotary movement relays 306 and 337, Fig. 4, energize and at the end of the rotary movement deenergize and transmit another impulse of current to magnet 338 of 110 switch MDS, which advances its wipers to third position. Wiper 308 is now connected to magnet 343 of the thousands digit register DR¹, and wiper 309 connects earth to the starting conductor 400. The earth on conductor 400 causes the sending switch SEN to transmit impulses in accordance with the exchange code which has been determined by the dialling of the first three digits 833 of the wanted number, and it is thought best at this 115 stage to defer the explanation of these operations and to describe the operation of the register switches DR¹, DR², DR³ and DR⁴ in registering the four digits 2, 3, 4, 5 of the wanted number. The dialling of the thousands digit 2 causes impulse relay 300 to

transmit two impulses to magnet 343 of the thousands register DR¹, Fig. 6, over conductor 343' which advances wiper 344 two steps. When the register DR¹ leaves its nor- 120 125 130

mal position off normal springs 345 prepare a circuit for release magnet 346.

Slow relay 306 is energized in series with magnet 343 and in conjunction with relay 5 337 transmits another impulse to magnet 338 of switch MDS which advances wipers 308 and 309 to fourth position. Wiper 308 in moving from third to fourth position, transfers the control circuit from magnet 343 to 10 magnet 349. No circuit changes are brought about by the further movement of wiper 309, since contacts 3 to 10, inclusive, are multiplied together.

When the hundreds digit 3 is dialled, relay 300 transmits three impulses over relay 306 and conductor 349' to magnet 349 of the hundreds register DR², which advances wiper 350 into engagement with the third contact in the bank of register DR². When 20 the register DR² leaves its normal position off normal springs 351 prepare a circuit for release magnet 352 and off normal springs 353 prepare a circuit for earthing conductor 401. At the end of this series of impulses 25 slow relays 306 and 337 transmit an impulse of current to magnet 338 and switch MDS which advances wipers 308 and 309 to fifth position. In a similar manner to the above, when the calling party dials the tens digit 30 4 and the units digit 5, a series of four impulses is transmitted to magnet 338' of the tens register DR³, and a series of five impulses is then transmitted to magnet 359 of the units register DR⁴.

Referring now to Fig. 4, the sending switch SEN is started by wiper 309 of switch MDS in third position connecting earth to starting conductor 400. The code in accordance with which the call is trunked to 40 the local exchange is one series of three impulses as will be seen from the trunking layout, Fig. 1, and accordingly the third set of contacts in the third level of the register switch BCR, which were selected by dialling the digits 833, is so cross connected at the IDF as to cause the transmission of one series of impulses. This is effected at the 45 IDF by connecting terminal 1 on the right hand side of the IDF to terminal 3 on the left hand side and terminals 2, 3, 4, 5 and 6 on the left hand side to terminal DCO on the left hand side by so called jumper wires. Starting conductor 400 extends to the sender control switch SCS, Fig. 6, where it is connected to the first six contacts in the bank 50 of wiper 364 and to wiper 365. Accordingly earth is connected to the No. 3 contact in the bank of stop wiper 230 of the sending switch SEN, Fig. 4, over conductor 400, 55 wiper 365 in normal position, conductor 392, wiper 330, terminal No. 1 on the right hand side of the IDF to terminal No. 3 on the left hand side, conductor 367, to the No. 3 contact in the back of stop wiper 230 of the 60 sending switch SEN.

At the same time a circuit is completed for the two-step starting relay 373 of the sending switch SEN as follows: earthed conductor 400, wiper 364 of switch SCS, Fig. 6, in first position, conductor 401, interrupter springs 374 on common driving motor, armatures 375, armature 376, armature 377 and their back contacts to the upper winding of two step relay 373 and battery. Relay 373 is marginally adjusted and only 75 operates armature 378' in this circuit. Armature 378', however, connects the upper and lower windings of relay 373 in series and it fully operates over the following circuit when the interrupter springs 374 are 80 opened: battery, upper and lower windings of relay 378 in series, working contact and armature 378', resting contact and armature 379, conductor 380, armature 381 and its working contact of relay 302, Fig. 5, to earth. 85 Relay 373 upon attracting its armatures 377 places the stepping magnet 214 of the sending switch SEN under the control of interrupter springs 374. Stepping magnet 214 energizes upon the closure of the interrupter 90 springs 374 and opens the impulsing contacts 321, which, however, are short circuited by armature 320 and its resting contact of slow relay 378'. Upon the opening of interrupter springs 374 magnet 214 deenergizes 95 and wipers 213 and 230 are advanced one step in which position stop wiper 230 engages a dead contact and wiper 213 and earthed contact. The latter completes a circuit for slow relay 378 which energizes and 100 prepares a locking circuit for stop relay 381 at armature 380 and removes the short circuit from impulsing contacts 321 at armature 320. The second time interrupter springs 374 open the circuit of magnet 214 105 the wipers 213 and 230 are advanced one more step, thus bringing the stop wiper 230 into engagement with the No. 1 contact in its bank, and also, since relay 378 is now energized magnet 214 opens at the impulsing contacts 321 the circuit of line relay 48 110 of the exchange selector ES, Fig. 2. The energizations and deenergizations of magnet 214 continue in quick succession under the control of the interrupter springs 374 115 until stop wiper 230 is advanced into engagement with the No. 3 contact, which is earthed at this time over conductor 367 and a circuit is completed for stop relay 381 which terminates the office code digit 3. Relay 381 closes 120 at armature 382 a locking circuit for itself, at armature 376 opens the circuit of stepping magnet 214, at 379 opens the circuit of two step start relay 373, at armature 383 short circuits the impulsing contacts 321 so as to 125 prevent their subsequent operation interfering with the switch control circuit and at 384 completes a local circuit for stepping magnet 214 including its over interrupter contacts 385 and wiper 213. By the closure of the lat- 130

ter circuit magnet 214 advances its wipers to normal position.

Each time magnet 214 opens its impulsing contacts 321 while slow relay 378 is energized and stop relay 381 deenergized the following circuit for line relay 48 of the exchange selector ES, Fig. 2, is opened: battery, upper winding of relays 48, 49, 56, 34', 34, 45, 132, 134, 113, 125, 202, 309, 310, 311, 399, 320, 321, 203, 128, 116, 135, 133, 46, 35', 50, 51, 65, to the lower winding of relay 48 and earth. Each time relay 48 deenergizes it transmits an impulse of current to the vertical magnet 55 over the following circuit: earth, armature 75 and its working contact, resting contact and armature 76, armature 54 and its resting contact, slow series relay 78, to vertical magnet 55 and battery. Since line relay 48 is deenergized three times, three impulses will be delivered to the vertical magnet 55 which accordingly raises its wipers 80, 81, 82, step by step until they stand opposite the third level of bank contacts. Slow relay 27 is energized at this time since relay 25 is energized over its lower winding in series with line relay 300 of the director Fig. 5. Relay 78 energizes in series with the vertical magnet 55 upon this first impulse of current being delivered to the latter, and, being sluggish, maintains its armature 79 attracted throughout the vertical movement. By the joint action of relay 78 and off normal springs 83, which close upon the first vertical step, a circuit is completed from earthed armature 75 over 76, 58, 79, 83 for stepping relay 59. Upon energizing, stepping relay 59 closes a locking circuit for itself at armature 84, and at armature 85 prepares a circuit for rotary magnet 86.

At the end of the vertical movement, series relay 78 deenergizes and completes at the normally closed contacts controlled by armature 79 a circuit for rotary magnet 86. Rotary magnet 86 thereupon energizes and advances wipers 80, 81, 82, into engagement with the first contact in the level opposite which they are now standing and, near the ending of its stroke, opens the circuit of stepping relay 59. Stepping relay 59 accordingly de-energizes and opens the circuit of the rotary magnet 86 at armature 85, whereupon rotary magnet 86 deenergizes also and again closes its interrupter contacts 87.

The further operation depends upon whether the trunk terminating in the first set of bank contacts is busy or idle. Assuming that it is idle, switching relay 53 energizes at once and switches the connection through to the trunk. In case it is busy, however, switching relay 53 is short circuited by the earth potential encountered on the busy test contact by test wiper 80 and does not energize. Stepping relay 59, however, is energized by this same earth potential and again closes the circuit of rotary magnet 86.

Whereupon the switch wipers are advanced into engagement with the next set of bank contacts. This alternate operation of stepping relay 59 and rotary magnet 86 continues, as described, until an idle trunk is reached. 70 If all the trunks in the selected level are busy the cam springs 88 are operated on the 11th contact being reached opening the circuit of switching relay 53, and closing a circuit for the busy signal which is transmitted from 76 the busy tone conductor BT to the calling party. We will assume, however, that the bank contacts in which the trunk comprising conductors 500-502, inclusive, is found to be idle. When such idle trunk is found, switching relay 53 being no longer short circuited, energizes in series with stepping relay 59. Stepping relay 59, however, does not energize at this time on account of the high resistance of switching relay 53. Upon energizing, switching relay 53 removes earth from armature 54 of line relay 48 at armature 76, disconnects test wiper 80 from the junction of its own winding and that of stepping relay 59 and connects it to the earthed 80 release trunk conductor 32' at armature 89, thereby making the seized trunk busy immediately and preparing the holding circuit, at armatures 49 and 65 disconnects conductors 70 and 71 from the windings of line relay 48 85 and extends them by way of wipers 81 and 82, trunk conductors 501 and 502 to the line relay 503 of the first selector S, Fig. 7. Relay 53 also completes a locking circuit for itself at armature 90, and at armature 94 disconnects 90 the earth at armature 75 from conductors 36', Fig. 2, 44, Fig. 3, and 200, Fig. 5; these conductors remain earthed at this time at armature 414 of relay 302, Fig. 5, thereby maintaining switching relay 129 of the director selector DS and switching relay 42 of the trunk relay group TR energized. 105

Returning now to the director, relay 381 also closes at armature 382 a circuit over conductor 386 for magnet 387 the sender control switch SCS, Fig. 6. Magnet 387 energizes but does not advance its wipers until magnet 387 deenergizes. This occurs by the deenergization of slow relay 378, Fig. 4, which is brought about by the return of wiper 213 to 110 normal position when the circuit of magnet 387 is opened by the deenergization of slow stop relay 381 and its wipers are advanced to second position. 115

The interval required for slow relays 378 and 381 to fall back one after the other, as described, is utilized by the selector S, Fig. 7, in effecting the change-over and trunk hunting operations. Since there is only one series of code impulses in the exchange code, the sender control switch SCS must now be advanced automatically through its second, third, fourth, fifth and sixth positions in order to prepare the circuits for the transmission of the thousands digit as soon as the sending switch SEN 125 130

has restored to normal. This is accomplished automatically, due to terminal DCO on the left hand side of the IDF being cross connected to terminals 2, 3, 4, 5, and 6 on the right hand side of the IDF instead of to any of the terminals which are associated with the bank of the sending switch SEN.

The circuit over which magnet 387 is automatically advanced may be traced as follows: battery, magnet 387, interrupter contacts 388, multiplied bank contacts 389, conductor 390, conductor 391, terminal DCO, multiplied cross connections to terminals 2, 3, 4, 5 and 6 on the right hand side of the IDF, wipers 331-335, inclusive, conductors 392-396, inclusive, second, third, fourth, fifth, and sixth contacts in the bank of wiper 365 of switch SCS, wiper 365, conductor 397, multiplied contacts 398 in the bank of wiper 364, to earthed conductor 400.

The above described operations of the sender control switch SCS have occurred in a very small fraction of a second and are completed long before the sender is in a position to transmit the next digit which is the first digit 2 in the wanted party's number, the exchange code 3 having been transmitted as described above.

As pointed out hereinbefore, the sending out of the exchange code was initiated responsive to the earthing of start conductor 400 by wiper 309 of the switch MDS and, it will be remembered, occurred after the third exchange digit has been registered. The start conductor 400, it will be noted, is connected with only the first six contacts in the bank of the start conductor control wiper 364 of switch SCS and accordingly the earth on start conductor 400 is not effective in again starting the sender after the switch SCS has moved beyond the sixth contact, as it has already done. The starting of the sending mechanism for the remaining digits in the number is controlled by the digit registers DR¹-DR⁴, inclusive, by means of which the four subscriber digits of a number are registered. It is obvious that a digit cannot be sent out before it is received and accordingly the sending mechanism must not be again started until the first digit register DR¹ has been operated.

The control of the starting circuit is governed by the off normal contacts of the digit registers DR², DR³ and DR⁴. The first register DR¹ does not exercise any control over the starting circuit and the sender is started to send out the first subscriber digit responsive to the second digit register DR² moving from its normal position and closing its off normal contacts 353. Then, since, it must send out the first digit before it can start sending out the second one, there is no danger of the sender overtaking the second register.

Similarly, the off normal springs 357 of the digit register DR³ control the transmission of the second subscriber digit, the off normal springs 362 of the digit register DR⁴, however, control the transmission of the third and fourth subscriber digits. It will be seen that the off normal contacts 362 earths conductor 406 which is multiplied to the ninth and tenth contacts in the bank of wiper 364, of the sender control switch SCS.

It is apparent from the above explanation that in case a calling party does not dial the first subscriber digit immediately after completing the dialling of the exchange selecting digit, the re-transmission is held up upon the termination of the exchange code and the sender is not again started until the conductor 401 is earthed responsive to the dialling of the second subscriber digit.

It is apparent that the same occurs in case the subscriber waits between the calling of the first and second subscriber digits. The same rule applies to the re-transmission of the third and fourth digits.

In the following description it will be assumed that the subscriber does not hesitate; but having once started completes the dialling of his number without waiting more than the usual time between successive digits, in which case it is quite obvious that the director does not catch up on account of the fact that it must wait until the first two subscriber digits are registered before it can start to re-transmit.

The stop conductor control wiper 365 is now in engagement with the bank contact in which the first subscriber digit stop conductor 399 terminates. Earth is accordingly extended over conductor 399 to wiper 344 of the first digit register DR¹ which wiper is in engagement with the second contact, which is connected to the second contact in the bank of stop wiper 230 over conductor 368. The initial circuit of the two step start relay 373 is again closed, this time by wiper 364 of switch SCS in seventh position and relay 373 closes the circuit of magnet 214 at armature 377 upon the deenergization of stop relay 381. The interrupter contacts 374 again intermittently open thereby driving the sending switch SEN around through the medium of the magnet 214 which also interrupts the outgoing control circuit at impulse contacts 321 each time it energizes after slow relay 378 has removed the short circuit from impulse springs 321. Relay 378 it will be remembered operates when wiper 213 makes its first steps from normal position.

Stop relay 381 is energized again, this time by stop wiper 230 encountering earth on the second digit stop conductor 368 and two impulses are sent out over the outgoing control circuit to the line relay 503 of the first selector S. Fig. 7. Each time line relay 503 deenergizes in response to the series of two interruptions produced in its circuit in the director, it closes a circuit for vertical magnet 509 as 130

follows: from earth, armature 511 and its resting contact, armature 512 and its resting contact, armature 515 and its working contact to vertical magnet 509 and the upper winding 5 of change over relay 505 in parallel to battery. Since line relay 503 is deenergized twice, two impulses will be delivered to the vertical magnet 509 which raises the wipers 527-529, inclusive, step by step until they stand opposite to the second level of bank contacts. Relay 505 energizes upon the first impulse of current being delivered to the vertical magnet 509.

By the joint action of relay 505 and off normal springs 522, which close upon the first vertical step, a circuit is completed from the earthed release trunk conductor 500, eleventh step rotary cam springs 533, working contact and armature 517, vertical off normal springs 20 522, for stepping relay 506. Upon energizing, relay 506 closes a locking circuit for itself at armature 520.

This circuit may be traced as follows: earth, working contact and armature 518, 25 working contact and armature 520, interrupter spring of rotary magnet 510, off normal springs 522 to relay 506 and battery. Relay 506 at armature 521 short circuits the lower winding of relay 505, thereby rendering the latter relay slow to release, and consequently 30 relay 505 remains energized during the series of impulses transmitted to the vertical magnet 509. Relay 506 at armature 518, short circuits the eleventh step cam springs 533. The purpose of these springs is to ensure that the 35 rotary magnet 510 will receive a standard impulse of current on the eleventh step.

At the end of the series of impulses delivered to the vertical magnet 509, relay 505 40 which is now slow to release, deenergizes and completes the circuit for rotary magnet 510, at the normally closed contacts controlled by armature 517, whereupon the rotary magnet 510 energizes and advances the wipers 527-529, inclusive, into engagement with the first set of bank contacts in the second level and near the end of its stroke opens the circuit of stepping relay 506 at its interrupter contacts. Responsive to this, stepping relay 506 deenergizes and opens the circuit of 45 rotary magnet 510 at armature 519, whereupon rotary magnet 510 deenergizes also and again closes its interrupter contacts.

In case the trunk terminating in the first 55 set of bank contacts is idle, switching relay 507 energizes immediately upon the above closure of the interrupter contacts and seizes the trunk. In this case, however, it will be assumed that the trunk terminating in the first set of bank contacts is busy in which case the test wiper 528 engages an earthed test contact and switching relay 507 is short circuited. Also stepping relay 506 energizes over wiper 528 and again closes a circuit for 60 rotary magnet 510, at armature 519, where-

upon rotary magnet 510 energizes again and advances the wipers 527-529, inclusive, into engagement with the next series of contacts.

This alternate operation of stepping relay 506 and rotary magnet 510 continues until 70 an idle trunk is reached. If all the trunks in this level are busy the cam springs 533-535, inclusive, will be operated on the eleventh step, switching relay 507 will be unable to energize and the calling party will receive 75 the busy tone over the following circuit: earth, busy tone, conductor ET, cam spring 535, armature 516 and its working contact, resting contact and armature 524, speaking conductor 501, wiper 81, working contact and 80 armature 49, conductor 70; condenser C, to conductor 20. It will be noticed also that cam springs 534 connect the intermittently earthed conductor IT to the upper winding of relay 505, the lower winding of relay 505 being no longer short circuited, relay 505 will now function as a quick acting relay and at 85 its armature, 516 intermittently connects busy tone and earth to conductor 501. In the present case this intermittent earth on conductor 501 has no effect but had the call originated from a manual exchange it would 90 serve to flash the operated supervisory lamps. Assuming, however, that the trunk comprising conductors 530-532, inclusive, and extending to the second selector S¹, is found to 95 be idle then switching relay 507 being no longer short circuited energizes in series with stepping relay 506. Stepping relay 506, however, does not energize at this time on account of the high resistance of switching relay 507. Upon energizing switching relay 507 disconnects earth from armature 512 of line relay 503 at armature 511, thereby opening the circuit of slow release relay 504; 100 transfers the test wiper 528 from the test circuit to the holding circuit at armature 526; and at armatures 524 and 525 disconnects the trunk conductors 501 and 502 from the windings of line relay 503 and extends, by way 105 of wipers 527-529, the bank contacts with which they are in engagement, and conductors 530-532 to the windings of the line relay of the selector S¹. The line and release relay (not shown) of the selector S¹ now energize 110 in the usual manner and the latter prepares the switch for operation. The switch S¹ is similar to the switch S and it is not thought necessary to describe its operation in detail.

In the director slow relays 378 and 381 deenergize after the interval for which they are adjusted, relay 378 opens at armature 380 the circuit of magnet 387 of the switch SCS. Fig. 6, which now advances its wipers into eighth or hundreds position. Stop relay 381 upon deenergizing again connects up the two step start relay 373. Assuming that the calling subscriber has already dialled the tens digit 4, conductor 405 will be earthed causing the sending switch SEN to restart immediately 125 130

relay 373 energizes. Since the hundreds digit in the number is 3, No. 3 contact in the bank of stop wiper 230 will be earthed over wiper 350 of the hundreds register DR², and conductor 367. The sending switch SEN will now transmit a series of three impulses over the outgoing control circuit, this time to selector S', Fig. 7, selector S' is identical with the selector S and accordingly raises its 10 wipers 536-538, inclusive, to the third level and selects an idle trunk assumed to be the trunk comprising conductors 539-541, inclusive, extending to the connector FS, Fig. 8.

After the operation of the sending switch 15 SEN in transmitting the hundreds digit, magnet 387 advances the sender control switch wipers to ninth or tens position. Assuming now that the calling party has completed the dialling of the units digit, conductor 403 will be earthed and since wiper 355 is now standing on its No. 4 contact, earth will be extended to the No. 4 contact in the bank of sending switch SEN over conductor 369. A series of four impulses is accordingly 20 transmitted by switch SEN to the connector FS, which raises its wipers to the fourth level of bank contacts. Magnet 387 of the sender control switch advances its wipers to the 25 tenth or units position with the result that wiper 364 connects earth to wiper 360 of the 30 units digit register DR⁴.

Since the ninth and tenth contacts in the bank of wiper 364 are multiplied together conductor 401 will be earthed, sending switch 35 SEN will be started, and since wiper 360 is in engagement with the No. 5 contact in its bank, a series of five impulses will be transmitted to the connector FS.

The operation of the connector switch FS, 40 Fig. 8, will now be explained in detail. When the series of impulses corresponding to the third digit four is transmitted over the control circuit of the director, the line relay 544 of the connector FS is momentarily deenergized four times and at each deenergization transmits an impulse of current to the vertical magnet 551 over a path which extends from earth by way of armature 554 and its resting contact, armature 555 and its working contact, off normal springs 556 and 558, the upper winding of change-over relay 546 and vertical magnet 551 in parallel to battery. By the operation of the vertical magnet the wipers 559-561, inclusive, are raised 45 step by step until they stand opposite to the fourth level of bank contacts. Relay 546 is energized in parallel with the vertical magnet 551 and at armature 562 short circuits its lower winding thereby rendering it slow to release and it holds up continuously during 50 the vertical operation of the switch. By the operation of this relay the vertical magnet circuit is preserved intact at armature 563 notwithstanding the shifting of the off normal springs, which occurs at the first vertical

step of the switch. At the end of the vertical movement, relay 546 deenergizes and transfers the operating circuit to the rotary magnet 552 at armature 563.

The last series of impulses comprise five 55 interruptions in the control circuit corresponding to the final digit 5 of the wanted number. Responsive to these interruptions the line relay 544 is deenergized five times and now sends impulses to the rotary magnet 552 over the following circuit: from earth, by way of armature 554 and its resting contact, armature 555 and its working contact, off normal springs 556 and 557, armature 563 and its resting contact, resting contact and 60 armature 564, armature 565 and its resting contact, rotary magnet 552 to battery. By the operation of the rotary magnet, the wipers 559-561, inclusive, are rotated step-by-step and are fully brought to rest into engagement with the particular set of bank contacts in which the line of substation A' is terminated. The upper winding of relay 549 is energized in parallel with the rotary magnet and at armature 566 short circuits 65 its lower winding thereby rendering the relay slow to release and it therefore remains operated during the rotary movement. In operated position, relay 549 connects the test wiper 560 to the winding of busy relay 548 70 at armature 567, at armature 568 closes an alternative point in the circuit of the rotary magnet to guard against the possibility of having this circuit opened by the operation of the test relay while the test wiper 560 is 75 passing over busy test contacts; and at armature 569 short circuits the resistance r which is normally short circuited by armature 570 of the busy relay 548 during impulse transmission.

The final series of impulses has now been received and the connector switch wipers 559-561, inclusive, have been placed in connection with the bank contacts of the called line. If the line is busy there will be an 80 earth potential on the test contact 572 and the busy relay 548 will be energized. When this relay operates it prepares a locking circuit for itself at armature 574 which is completed when the slow relay 549 falls back 85 an instant later, opens the rotary magnet circuit at armature 564 and at armature 570 connects the common busy tone and busy flash lead over the resting contact and armature 569, resistance r normally closed contacts controlled by armature 575 to the speaking conductor 541.

By this operation an audible busy signal will be transmitted to the calling party from the busy tone conductor BF. The busy flash 90 signalling current from conductor BF comprising battery and earth alternately, will have no effect in this connection but would flash an operator's supervisory signal in her cord circuit had the connection originated 95

from a manual exchange by alternately connecting battery and earth to conductor 541 through resistance r .

Suppose now that the called line is idle 5 when connection therewith is attempted. Under these circumstances there will be no earth on test contact 572 and busy relay 548 will not be energized. Then when the slow relay 549 falls back a circuit is completed for 10 switching relay 550 which may be traced from earthed release trunk conductor 540, armature 547 and its resting contact, the upper winding of switching relay 550, resting contact and armature 567, test wiper 560, bank 15 contact 572, cut-off relay 577 of the line switch LS² and stepping magnet 578 to battery. Relays 550 and 577 are energized in series over this circuit, and the latter relay is effective in disconnecting the normal battery 20 and earth connections in the line switch LS² from conductors 571 and 573, respectively.

At the connector FS, when the switching relay 550 pulls up, it establishes a locking circuit for itself at armature 579, earths the test 25 wiper 560 at armature 580, opens the rotary magnet circuit at armature 565, and at armatures 581 and 582 connects up the two line wipers 559 and 561. By the latter operation a signalling circuit is established whereby 30 ringing current from the generator GEN is intermittently sent out over the called line to operate the bell at substation A'. The return path for the ringing current includes the upper winding of the ring cut off relay 547 35 and when the wanted party answers the relay 547 is operated. Upon energizing relay 547 establishes a locking circuit for itself at armature 583, breaks the ringing circuit at armatures 584 and 585, and at the working contacts of these armatures finally completes the 40 talking connection. Current is now supplied to the substation A' through the windings of the double wound reversing relay 543 which is accordingly energized. Relay 543 45 upon energizing reverses the incoming trunk conductors 539 and 541 as regards their connections with the line relay 544 and consequently the current flowing over the speaking 50 conductors and through the polarized relay F in the trunk relay group TR, Fig. 2. Relay F energizes at this time and completes at armature 75 the circuit for operating the calling party's meter M. Meter M upon operating registers the call and completes at its own 55 armature a locking circuit for itself independently of armature 75 of the polarized relay F. This locking circuit prevents any subsequent operation of relay F during the conversation from operating the meter M.

60 Returning now to the director the energization and deenergization of the sender control switch magnet 387, Fig. 6, during the transmission of the final series of impulses causes the sequence switch wipers to 65 be advanced to switching position, where-

upon the following circuit is established for switching relay 205, Fig. 4: from earth, wiper 365 in switching position, conductor 410, normally closed contacts controlled by armature 411, to relay 205 and battery. Relay 205 establishes at armature 411 a locking circuit for itself, breaking the initial energizing circuit at the same time, opens at armature 375 the circuit of two step relay 373, removes at armature 311 the short circuit from resistance 412^a, at armature 412 opens the initial energizing circuit for the two step relay 216, and at armature 204 removes the holding earth from test conductor 200. Since switching relay 129 of the director selector DS, Fig. 3 and switching relay 42 of the trunk relay group TR, Fig. 2, are maintained energized at this time over conductor 200 which is earthed over conductor 370 at armature 414 of relay 302, Fig. 5, the 70 75 80 85 operation of relay 205 will bring about the release of switching relays 129 and 42.

Relay 129 upon deenergizing opens at armature 104 the circuit of impulse relay 300, Fig. 5. Relay 300 accordingly deenergizes 90 and opens at armature 301 the circuit of relay 302. Switching relay 42 upon deenergizing connects the upper winding of battery feed relay 25 to conductor 20 before it disconnects it from conductor 33' at armature 24 and relay 25 now feeds battery to the calling subscriber through its upper and lower windings. Relay 42 at armature 60 prepares a circuit for restoring the secondary switch SLS to normal which operation however does not take place until the conversation is terminated by the calling party replacing his receiver upon the switchhook; and at armatures 24, 56, 50 and 38 disconnects wipers 33, 34, 35, and 36, respectively, of the 95 100 105 secondary line switch SLS.

Switching relay 129 upon deenergizing, completes at armature 111 a circuit for release magnet 119 which restores the switch to normal position, in which position the off-normal springs open the circuit of the release magnet.

Returning now to relay 302, Fig. 5, which deenergizes shortly after relay 300, and opens the circuit of relay 209 at armature 414 and 115 at armature 381 the locking circuit for relay 205. Relay 209 upon deenergizing connects earth at armature 210 over conductor 390 to the upper bank of switch SCS in order to advance the sender control switch wipers to 120 their normal position; at armature 219 earths the release conductor 220 thus completing parallel energizing circuits for release magnet 348 of the master digit switch MDS and release magnet 371 of the register BCR, Fig. 5, and the release magnets 346, 352, 358, and 363 of the digit registers DR¹-DR⁴, respectively. Relay 209 also connects wiper 213 of the sending switch SEN with magnet 214 at armature 211. This operation, however, is 125 130

of no particular importance, ordinarily, owing to the fact that the sending switch is restored automatically by the completion of the same circuit at armature 384 of stop relay 381. As described in the foregoing the connection is switched through and the director is released as soon as the final series of impulses has been transmitted. The director is thus used only during the actual 10 setting up of the connection and is rendered accessible to other subscribers as soon as the connection is completed. After the connection has been switched through it is the same in all essential particulars as an ordinary automatic connection.

When the conversation is finished the calling and called parties will replace their receivers. The release of the connection is under the control of the calling party. When 20 the receiver is replaced at the calling station, battery feed relay 25 of the trunk relay group TR, Fig. 2, deenergizes and opens the circuit of release relay 27 at armature 26. Relay 27 upon deenergizing completes at armature 75 the following circuit for release magnet 91 of the exchange selector ES. Earth, armature 75, and its resting contact, off normal springs 92, release magnet 91 to battery. By 25 the operation of the release magnet the exchange selector ES is restored to normal the circuit of the release magnet being opened at the off normal springs 92 when the switch shaft reaches its normal position. Relay 27 also closes the following circuit at armature 30 for stepping magnet 31 of the secondary switch SLS. Battery, stepping magnet 31, conductor 41, armature 40 and its resting contact, armature 30 and its resting contact, resting contact and armature 60, conductor 40 37', home wiper 37 and the earth bank contacts 70. Stepping magnet 31 accordingly rotates the wipers 33-37, inclusive, one step each time an earth bank contact 70 is encountered by wiper 37 and as a contact 770 is provided for each set of bank contacts except 45 for the home position set, the wipers 33-37 are therefore restored to their normal positions, where the circuit for stepping magnet 31 is opened by the home wiper 37 engaging a 50 dead contact.

Relay 27 also disconnects at armature 29 earth from test conductor 21 of the calling party's line switch LS and from one side of the switching relay 53 of the selector ES, Fig. 2. By the removal of earth from test conductor 21 the holding circuit for the line switch LS is opened and cut off relay 5 de-energizes. Upon deenergizing relay 5 completes the following circuit for stepping magnet 7. Battery, stepping magnet 7, inter- 55 rupter contacts 14, armature 17 and its resting contact, armature 15 and its resting contact, home wiper 29 to the earthed bank contact 9'. Stepping magnet 7 accordingly ad- 60 vances its wipers 8-12, inclusive, each time 65

wiper 9 engages an earth contact 9' and as each set of bank contacts is provided with an earthed contact 9' except the home position set, stepping magnet 7 will continue to operate until the home wiper 9 engages a 70 dead contact: The removal of earth from one side of the switching relay 53 causes the latter to deenergize. Relay 53, upon deenergizing, opens at armatures 49 and 65 the circuit of line relay 544 of the connector FS, 75 Fig. 8. Line relay 544 upon deenergizing opens the circuit of release relay 545. Release relay 545 upon deenergizing removes earth from release trunk conductor 540 at armature 586 and at armature 555 completes the usual 80 circuit for release magnet 553. The removal of earth from release trunk conductor 540 will open the circuit of switching relay 507 of the first selector S and the corresponding switching relay of the second selector 21. Switching relay 507 upon deenergizing completes a 85 circuit for release magnet 508 and the latter restores the switch to normal. A similar circuit is completed for the release magnet of the second selector S¹ and this switch is 90 also restored to normal. It will be seen that the removal of earth from test conductor 500 of the exchange selector ES by the deenergization of slow relay 27 of the trunk relay group TR will not bring about the release of 95 the succeeding switches as the test conductor 500 remains earthed at this time by armature 586 of the release relay 545 of the final selector FS.

Supervisory features.

In the foregoing description it was assumed that the calling subscriber effected the dialing of the wanted number in a proper manner, and in order to explain certain supervisory features of the director it will first be assumed that the calling party removes his receiver and commences to dial before he receives the dial tone from the director selector DS. Under these conditions the secondary switch SLS will probably be hunting for an idle director selector and relay 42 of the relay group TR will not have energized. When the calling party dials the first digit, relay 25 which will probably now be energized 105 over the calling party's loop, will deenergize and open at armature 47 the hereinbefore traced initial circuit for line relay 48 of the exchange selector ES. Relay 48 upon deenergizing completes at armature 71 the following 110 circuit for the two step supervisory relay 62: earth, armature 75 and its working contact, resting contact and armature 76, armature 71 and resting contact, resting contact and armature 95, resting contact and armature 61, lower winding of two step relay 62 to battery. Relay 62 upon energizing in 115 this circuit only operates its upper armature which prepares a circuit for fully operating relay 62. Relay 48 upon deenergizing also 120

completes at armature 54 the following circuit for vertical magnet 55: earth, armature 75 and its working contact, resting contact and armature 76, armature 54 and its resting contact, slow series relay 78 and vertical magnet 55 to battery. Vertical magnet 55 energizing and raises the switch shaft one step thereby closing the off normal contact 83. Slow relay 78 energizes in series with the vertical magnet 55, but does not complete a circuit for stepping relay 59 as the circuit for this relay is open at armature 58 of switching relay 42 and consequently no hunting operation will take place. By the closure of off normal contact 83 the following circuit for switching relay 53 is completed: from the earthed release trunk conductor 21, normally closed eleventh step cam springs 88, switching relay 53, normally closed contacts controlled by armature 90, interrupter springs 87, off normal springs 83, stepping relay 59 to battery. Stepping relay 59 does not energize in this circuit on account of the high resistance of switching relay 53 but the latter relay does. Relay 53 upon energizing opens at armature 76 the initial energizing circuit for two-step relay 62 which now fully energizes since both its windings are now in series one side being connected to battery and the other to the earthed release trunk 21.

Relay 53 also connects the number unobtainable tone conductor NUT to the lower speaking conductor 23 at armature 72 (relay 62 now having armature 97 attracted); at armature 39 opens the circuit of stepping magnet 31 of the secondary switch SLS thereby preventing it from taking a director selector into use; and at armature 76 opens the circuit of vertical magnet 55 in order to prevent subsequent impulses from operating the switch ES. Supervisory relay 62 upon energizing, completes at armature 98 a circuit for the supervisory lamp SL.

We will now assume that the calling party waits for the dial tone, i. e., seizes an idle director selector, but does not dial in any digits. Under these conditions relays 103 and 105 of the director selector DS energizes as before. Relay 105 connects up the time pulse conductor TPC to the lower winding of the two step time relay T at armature 109 over the following circuit: time pulse conductor TPC, armature 150 and its resting contact, armature 109 and its working contact, lower winding of time relay T to battery. Relay T energizes upon the time pulse conductor TPC being earthed by a timing device not shown, which earths the conductor TPC for example once every four seconds, and operates only its armature 151. Upon earth being removed from the time pulse conductor TPC relay T fully energizes over the following circuit: battery, lower winding of relay T, working contact and armature 109, upper winding of relay T, working contact and armature 151, working contact and armature 106, resting contact and armature 111 to earth. Relay T upon energizing opens the circuit of the rotary magnet 124 and prepares a circuit for 70 earthing conductor 43 at armature 152, and at armature 150 opens its initial energizing circuit and prepares a circuit for stepping relay 120. The next time the timing device earths the conductor TPC a circuit is completed for stepping relay 120. Relay 120 upon energizing short circuits the lower winding of relay 25 of the trunk relay group TR, Fig. 2, over the following circuit: earth, working contact and armature 107, normally 80 closed contacts controlled by armature 117, armature 123 and its working contact, armature 152 and its working contact, conductor 153, normally closed contacts controlled by armature 104, conductor 43, wiper 33, conductor 33', armature 24 and its working contact, conductor 20, wiper 8, working contact and armature 18, conductor 2, conductor 3, armature 19, and its working contact, wiper 12, conductor 23, to the lower winding of relay 25. 90

Relay 25 being energized at this time, over its lower winding in series with relay 103 of the director selector DS deenergizes. Relay 25 upon deenergizing opens at armature 26 the circuit for relay 27. Relay 27 upon deenergizing completes the initial energizing circuit for the two-step relay 62 at armature 75 as follows: earth, armature 75 and its resting contact, working contact and armature 61, lower winding of relay 62 to battery. Relay 62, however, only operates its upper armature at this time and prepares a circuit for energizing both its windings in series. 100

When the earth is removed from the time pulse conductor TPC by the timing device, relay 120 deenergizes and disconnects earth from conductors 153, 43, 33', 20 and 23, thereby removing the short circuit from the lower winding of relay 25 which energizes again in series with relay 103 of the director selector DS. Relay 25, upon energizing again completes the circuit for relay 27 at armature 26. Relay 27, upon energizing earths conductor 32' at armature 29 and at armature 75 opens the initial energizing circuit for relay 62. 110 The latter relay now energizes fully since both its windings are energized in series, the upper armature being connected to the earthed armature 57. Relay 62 upon energizing completes a circuit for the supervisory lamp SL at armature 98, and opens the circuit of switching relay 42 at armature 93. Switching relay 42 upon deenergizing restores conductors 32', 33', 34', 35', 36', and 37' to normal condition at armatures 57, 24, 56, 50, 38, and 60, respectively. Relay 42 also at the make before break contacts of armature 24 connects the upper winding of relay 25 in series with the calling party's loop, and at the same armature opens the circuit of relay 103 120

every four seconds, and operates only its armature 151. Upon earth being removed from the time pulse conductor TPC relay T fully energizes over the following circuit: battery, lower winding of relay T, working contact and armature 109, upper winding of relay 125 130

of the director selector DS. Relay 103 accordingly deenergizes and opens the circuit for relays 105 and T at armature 106 both of which deenergize before the next earthed time pulse is connected to the time pulse conductor TPC. The director selector DS is now restored to normal condition and free to be taken into use again by another secondary line switch.

10 In the trunk relay group relays 25, 27, and 62 are energized and in the exchange selector ES relay 48 is energized in the loop circuit including the upper winding of G, right hand winding of F, lower winding of G and armature 47 of relay 25 and maintains the circuit of vertical magnet 55 open at armature 54.

15 Relay 25 is now energized over the calling party's loop and controls the release of relays 27, 62 and 48. The next impulse dialled by the calling party will operate relay 25 which will now open the circuit of relay 48 at armature 47. Relay 48 upon deenergizing will complete the hereinbefore described circuit for vertical magnet 55 which will make one step and close the off normal springs 83, whereupon relay 53 will energize in series with stepping relay 59. Relay 53 completes a locking circuit for itself at armature 90; at 20 armatures 49 and 65 disconnects relay 48 to prevent subsequent impulses from operating the vertical magnet 55 and at armature 72 connects number-unobtainable tone NUT to the lower speaking conductor 23.

30 The calling subscriber upon hearing the tone replaces his receiver upon its rest whereupon relay 25 deenergizes and opens the circuit of relays 62, 53 and 27. Relays 62 and 53 deenergize first and then the relay 27 which completes at armature 30 the circuit for restoring the secondary switch SLS to normal and at armature 75 a circuit for release magnet 91 and at armature 29 removes earth from the release trunk conductor 21 whereupon relay 5 deenergizes and completes a circuit for 35 restoring the line switch LS to normal.

Assuming that the calling party waits for the dial tone and only dials in the first exchange code digit. Under these circumstances the director selector DS will be set in the hereinbefore described manner to take into use a director and relays 209, 300 and 302 in the director will energize as before. Now the first time pulse on conductor TPC of the director equipment, Fig. 4, will energize the two-step time relay 216 over armatures 215, 412, 230 and the lower winding of relay 216. Relay 216 being marginally adjusted only attracts its upper armature 221 in this circuit which prepares an energizing circuit for fully operating the relay. Now since the calling party does not dial in any further digits, relay 306 will not be energized and consequently when the earthed time pulse is removed 40 from conductor TPC relay 216 energizes over

the following circuit: battery, lower and upper windings of relay 216 in series, armatures 221, 217, and 336, to earth, and attracts its armature 230. The next time pulse conductor TPC is earthed the following circuit is completed for relay R: earthed conductor TPC, armatures 215, 412, 230, conductor 231, relay R to battery. Relay R upon energizing earths the impulsing conductors 201, 131, 43, 33', 20, and 23, at armature 273, thereby short circuiting the lower winding of relay 25 in the trunk relay group TR, Fig. 2 and opens the loop circuit over which relay 48 is now energized at armature 309. Relays 25 and 48 accordingly deenergize and supervisory lamp SL is 45 lighted, the number unobtainable tone transmitted to the calling party and the director selector released in the manner hereinbefore described.

50 Relay 300, Fig. 5, is maintained energized by relay R which latter relay deenergizes when earth is disconnected from the time pulse conductor TPC opening the circuit of relay 300. Relay 300 opens the circuit of relay 302 and relay 302 opens the circuit of relay 209. Relay 209 deenergizes and earths release conductor 220 whereby any register switches in an off normal position are released.

55 It will be readily understood from the foregoing that should the calling party delay to dial between the digits of the exchange code or between the digits of the wanted number that relay 306 will be deenergized after the last series of impulses dialled and that the previously described operations will take place upon the two-step time relay 216 energizing.

60 A further feature in connection with the director supervisory arrangement resides in lighting the supervisory lamp SL if a call has been properly set up and when the conversation is finished the called party hangs up his receiver but not the calling party.

65 Assuming that the called party hangs up his receiver, but not the calling party, the direction of current over the speaking conductors 501 and 502 will be reversed upon the deenergization of the reversing relay 543 of the conductor FS, Fig. 8. Responsive to this reversal the polarized relay F in the trunk relay group TR, Fig. 2, will deenergize. Upon deenergizing relay F completes the following circuit for supervisory lamp SL: battery, lamp SL, armature 98 and its resting contact, resting contact and armature 75 of relay F, conductor 22, wiper 11, working contact and armature of meter M to earth.

70 It should be understood that the supervisory lamp above referred to can be connected to any auxiliary type of alarm desired, for instance a three minute audible alarm.

75 If the sending apparatus in the director should for any reason fail to function cor-

rectly relay 205, Fig. 4, will, of course, not be operated and consequently the time pulse conductor TPC will become effective to bring about the energization of the two step relay 216. As before relay 216 will bring about the operation of relay 314, Fig. 5, which will earth conductor 201 at armature 273 whereupon relay 25 in the trunk relay group will be short circuited and deenergize with the result that the director will be released and the supervisory lamp SL lighted, and a tone current connected to the calling line in the manner hereinbefore described. Should the calling party dial a number which does not correspond to a working exchange the director will be released, the supervisory lamp lighted and the tone placed on the calling line. It will be noted that the lower winding of relay 314 is connected to the dead level terminal DL on the left hand side of the IDF and consequently if the DL terminal is cross-connected to the first contacts of all the dead level numbers, wiper 330 will earth the DL terminal when a number is dialled which does not correspond to a working exchange and bring about the energization of relay 314 with the hereinbefore described results.

Automatic connection to operator's position.

In order to explain the feature of the invention whereby a director is adapted to be taken into use over different paths and to operate in a manner characteristic of the path over which it was taken into use, and the feature whereby a director is adapted to operate automatically to control the setting up of a connection to an operator's position by being taken into use over a particular path. We will assume that the calling party at substation A desires to establish connection with the operator in the manual exchange No. 4. Although the subscriber at substation A gains access to a three digit director by removing his receiver, the connection with the toll exchange is established by dialling the digit 0 only, no further digits being required as will be understood from the following description. Assuming the calling subscriber has removed his receiver and that his line switch LS seizes an idle trunk relay group TR and that the secondary line switch SLS takes into use the director equipment DS and D. Upon dialling the digit 0, ten impulses will be delivered to the vertical magnet 110 of the director DS and the wipers 113-116, inclusive, will be raised opposite to the tenth level whereupon the rotary magnet will rotate the wipers 113-116, inclusive, until an idle line is found in that level. Assuming the conductors 250-252, inclusive, terminating in bank contacts 253-256, inclusive, are the first to be found idle. Since conductors 250-252 are multiplied to conductors 200-203, inclusive, the director equipment shown in Figs. 4, 5, and 6 will be taken

into use. It should be noted, however, that the multiplied connections between the bank contacts 125 and 128, the bank contacts 256 and 253 are reversed.

In the director equipment relays 300, 302, 70 209, energize in the manner hereinbefore described. In the exchange selector ES, Fig. 2, relay 48 is now maintained energized in the hereinbefore described loop circuit including the left hand winding of the polarized relay 75 316 and it will be remembered that this relay did not energize in this circuit as the current flowing in its left and right hand windings were in opposition. Since conductors 252 and 253 are now reversed with respect to conductors 202 and 203, polarized relay 316 now energizes. Upon energizing, relay 316 completes a locking circuit for stop relay 381 at armature 261 and at armature 254 completes the following circuit for relay S: battery, 80 85 relay S, conductor 255, working contact and armature 234, conductor 256, conductor 257, terminal X, conductor 258, wiper 309 of the master digit switch MDS in normal position and earth. It may be mentioned here that in 90 the three digit director system conductor 258 is connected to terminal X and in a two digit director system to terminal Z. Relay S upon energizing closes a locking circuit for itself at armature 259, at armature 260 earths the 95 starting conductor 400 and at armatures 318 and 313 restores the connection to the left hand winding of the polarized relay 316 to normal whereupon the said relay deenergizes. Relay S also connects wipers 330-335, inclusive, of the register switch BCR to conductors 100 262-267, inclusive, at armatures 268-273, inclusive, respectively. Conductors 262-267, inclusive, are so connected at the cross connection block IDF as to cause the sending 105 switch SEN to send out the necessary series of impulses to route the call to the toll exchange. In the present connection the sending switch SEN will send out ten impulses to raise the exchange selector ES to the tenth 110 level. It will then rotate automatically in search of an idle repeater leading to the toll exchange. The sending switch will be started in the manner hereinbefore described as soon as relay S earths the starting conductor 400 115 at armature 260.

In known director systems for this purpose a switch has been provided which responds to the first digit dialled to select an idle B and C digit register corresponding to that 120 digit, and when an operator is required the digit 0 has been dialled and special directors designed to control the operation of the switches so as to connect with an operator's position have been specially provided. Usually 8 levels of the director selector switch have been multiplied for gaining access to eight different classes of directors, the first level being normally left out and the tenth level being connected with special directors. 125 130

It will therefore be seen that by means of the present invention it is possible to eliminate entirely these special directors.

Two digit director system.

- 5 In order to describe the improvement whereby the director D is adapted to be used in either a two or three digit system. It will be assumed now that the calling party A is 10 connected to a two digit system, that is a system in which the wanted exchange is selected by dialling two digits instead of three. A detailed description of such a system is described in British Patent No. 200,484.
- 15 Assuming that the calling subscriber at station A removes his receiver and that his line switch seizes the trunk conductors 20-23, inclusive, of the trunk relay group TR and that the secondary line switch SLS seizes 20 conductors 200-203, inclusive, of the director D. It being understood of course, that director selectors DS are not provided in two digit systems and that the secondary line switch SLS has direct access to the directors such 25 as D. When the director D is intended for two digit working the normal post-springs NPS are connected as shown and adapted to operate on the tenth vertical step of the register BCR. Moreover conductor 258 of the 30 master digit switch MDS is connected to terminal Z, conductor 270 of the off normal springs 271 to the battery and dial tone conductor DT and conductors 262-267, inclusive, to the first set of bank contacts in the tenth 35 level of the register BCR. When the secondary line switch SLS seizes the director D, switching relay 42 energizes as before. Relay 48, however, of the exchange selector ES is now maintained energized over two circuits, one including both its windings and the 40 closed loop in the director D over conductors 202 and 203, and the other circuit includes the upper winding of relay 48, conductor 202 of the director D, terminal Z, conductor 258, 45 wiper 309 of the switch MDS to earth. Relay 300 is energized as before over the impulsive conductor 201, the calling party's loop and the lower winding of relay 25.
- The calling party receives the dial tone 50 from conductor DT, Fig. 5, off normal springs 271, armature 272 and its working contact of relay 302, resting contact and armature 273 of relay R to conductor 201. Upon the calling party dialling the two code digits and the subscribers' digits of the wanted number 55 the director D is operated in the hereinbefore described manner to register the digits and retransmit them to the wanted exchange. Should the calling party dial the digit 0 in 60 order to obtain connection with an operator's position, the register switch BCR will be raised to the tenth level, and since there is no reversal in the trunk conductors 202 and 203 the polarized relay 316 and relay S will not

be operated as in the case of a three digit system when the digit 0 is dialled. Instead, the normal post springs NPS will operate on the tenth vertical step of the register switch BCR and the following circuit will be completed for the rotary magnet 342 of the register BCR: battery, rotary magnet 342, normal post spring 274 and its working contact, conductor 340, conductor 240, working contact and armature 339 of relay 337, resting contact and armature 336 of relay 306 to earth. 65 It will be remembered that relay 306 was energized in series with the vertical magnet 304, during the series of impulses transmitted to the vertical magnet 304 and deenergized shortly after its termination. 70

By the deenergization of relay 306 the above traced circuit is completed for rotary magnet 342, and in parallel therewith the usual circuit for the stepping magnet 338 of the switch MDS. 80

Rotary magnet 342 accordingly rotates the wipers 330-335, inclusive, into engagement with the first set of bank contacts in the tenth level and magnet 338 advances the wipers 308 and 309 one step upon the deenergization of relay 337 which occurs shortly after the deenergization of relay 306. The first set of bank contacts in the tenth level of the register BCR it will be remembered are multiplied to conductors 262-267, inclusive, which 90 are so cross connected at the IDF as to cause the sending switch SEN to send out the necessary digits to route the call to an operator's position. 95

The sending switch SEN is started by wiper 309 being moved one step upon the deenergization of magnet 338 in which position starting conductor 400 is earthed over the following circuit: earth, wiper 309 in second position, normal post springs 276, multiplied 100 contacts in the bank of wiper 309 to conductor 400. 105

The supervisory features described in connection with the three digit system also become operative in the two digit system and it is not thought necessary to describe them again in detail. The connection of conductor 258 to the terminal Z is as previously stated provided for holding relay 48 energized when its circuit is opened by relay R at armature 309 which as will be readily understood is energized in the two digit system in case when the calling party waits for the dial tone, dials the first code digit and then fails to dial any further digits. The reason for not wanting to operate relay 48 in the trunk relay group TR, Fig. 2, on two digit systems is to prevent the number unobtainable tone being connected to a faulty line. By holding relay 48 energized in this case (i. e. when the calling party has merely seized a director but not dialled in any digits), the same result is produced as when a calling party seizes 110

115

120

125

a director selector and does not dial in a three digit system.

Interexchange automatic to automatic direct.

5 In order to explain the feature of the invention whereby direct interexchange connections are set up over trunk lines which are not provided with repeaters, we will assume that the calling subscriber at substation A in 10 the automatic exchange No. 1 desires to set up a connection to the subscriber at the substation A² in the automatic exchange No. 2. The digits dialled by the calling party to gain access to the wanted station A² are 8, 15 7, 6, 2, 3, 4, 5, and as will be seen from the trunking layout, Fig. 1, the first three digits 8, 7, 6, must be converted into the code digits 6, 3, in order to set the exchange selector ES in the No. 1 exchange to the sixth level and 20 the exchange selector ES¹ in the automatic exchange No. 2 to the third level.

Assuming that the calling party at the station A removes his receiver and that his line switch LS seizes the idle trunk relay group 25 TR, Fig. 2, and that the secondary line switch SLS seizes the idle director selector DS, Fig. 3, the calling party will now receive the dial tone from the director selector DS and will then dial the digits 8, 7, 6, followed by the 30 digits 2, 3, 4, 5. The first series of impulses will set the director selector DS to the eighth level, whereupon it will hunt in search of an idle director, and assuming that the bank contacts 125-128, inclusive, of the director 35 equipment shown in Figs. 4, 5 and 6, are the first to be found idle, then the next series of impulses will actuate the vertical magnet 304 of the register switch BCR and the magnet 304 will raise the wipers 330-335, inclusive, 40 opposite to the seventh level. At the end of the series of impulses slow relay 306 will de-energize and an impulse of current will be transmitted to the stepping magnet 338 of the master digit switch MDS which will advance 45 its wipers one step thereby connecting up the rotary magnet 342 in the manner hereinbefore described. The third series of impulses in the exchange code will cause the rotary magnet 342 to rotate the wipers into engage- 50 ment with the sixth set of contacts in the seventh level, and at the end of this series of impulses the slow relay 306 will again de-energize and the wipers of the master digit switch will be advanced another step, and in 55 this position wiper 309 earths starting conductor 400, and the impulse sender commences to send out the digits 6, 3 to route the call to the automatic exchange No. 2. The subscriber digits 2, 3, 4, 5, will be recorded on 60 the registers DR¹ to DR⁴ and retransmitted in the manner hereinbefore described. It will be understood of course, that the sixth set of contacts in the seventh level of the register switch BCR are cross connected at 65 the IDF in such manner as to cause the digits

6, 3 to be sent out by the sending switch SEN. Responsive to the transmission of the first series of impulses sent out by the director, the exchange selector ES, Fig. 2, will be raised to the sixth level and then automatically rotated in search of an idle trunk in the manner hereinbefore described. 70

Assuming that the bank contacts 600 to 602, inclusive, are the first set to be found idle in the sixth level, then the switching relay 75 53 of the exchange selector ES will energize and extend the outgoing impulsing circuit over wipers 81-82 to the inter-exchange trunk conductors 603 and 604. It will be noted that the test wiper 80 is earthed at this time and 80 therefore marks test contact 600 engaged. If it had been necessary to route this call over two selectors in the automatic exchange No. 1, the earth on the test wiper 80 would serve to hold up the switches in this exchange 85 throughout the connection. When the next digit 3 is sent out by the director the line relay 605 of the exchange selector ES' repeats three impulses to the vertical magnet 609 which raises the wipers 627-629, inclusive, 90 opposite to the third level. At the end of this series of impulses slow relay 607 deenergizes and connects up the rotary magnet 610. Rotary magnet 610 thereupon rotates the wipers 627-629, inclusive, in search of an idle trunk. 95 Assuming the trunk comprising conductors 630-632, inclusive, is the first one found idle, the rotary movement will stop and switching relay 612 will energize in series with stepping relay 608 and extend the trunk conductors 603 100 and 604 to trunk collectors 630 and 632, respectively. Switching relay 612 is maintained energized at this time by the earth at armature 613 of slow release relay 606, and subsequently by the earth fed back from the 105 second selector S⁵ over release trunk conductor 631. It being understood of course, that this earth is fed back before slow relay 606 has had time to deenergize.

Since the exchange selector ES' is similar 110 to the selector S except that the release trunk conductor 614 does not extend back to the exchange selector ES, it is not thought necessary to describe its operation in detail.

Responsive to the first series of subscriber 115 digits sent out by the selector S⁴ is raised to the second level and thereupon hunts for an idle trunk in that level, which trunk we will assume is the one comprising conductors 639-641, terminating in the second selector 120 S⁵. The next series of subscriber digits sent out by the director will operate the second selector S⁵ to the third level, which will thereupon hunt for an idle trunk leading to a connector switch having access to the wanted 125 subscriber A². The third and fourth series of impulses will set the connector switch on the bank contacts of the wanted subscriber's line whereupon he will be signalled in known manner. The selectors S⁴ and S⁵ and the con- 130

neator FS^2 are similar to the selectors S and S^1 and the connector FS and it is not thought necessary to describe their operations in detail.

- 5 The line relay of the connector FS^2 will be energized over the trunk conductors 603 and 604 in series with the impedance coil G and right hand winding of the polarized relay F of the trunk relay group TR , Fig. 2. The line 10 relay will maintain its associated release relay energized and the latter relay will maintain the release trunk conductor 650 earthed, thereby holding up the switches S^5 and S^4 in the usual manner. When the wanted party 15 replies the reversing relay in the connector FS^2 will reverse the direction of current over the trunk conductors 651 and 652 whereupon current will be reversed through the right hand winding of the polarized relay F which will 20 now energize and complete a circuit for the meter M .

When the conversation is finished the subscribers at stations A and A^2 will replace their receivers and the connection will be 25 released in the manner hereinbefore described.

Interexchange - automatic to automatic through an intermediate automatic.

- 30 In the previous connection from substation A in the automatic exchange No. 1 to substation A^2 in the automatic exchange No. 2 direct trunks are used between the exchange selector ES and the exchange selector ES' as 35 there was no necessity to provide repeaters for holding up the exchange selector ES or for repeating the busy flash had the call originated at a manual exchange for instance the manual exchange No. 4.
- 40 In a connection from the substation A in the automatic exchange No. 1 to the substation A^3 in the automatic exchange No. 3 a repeater is necessary in the inter-exchange 45 trunk between the exchange selector ES' in the No. 2 automatic exchange and the exchange selector ES^4 in the automatic exchange No. 3 in order to hold up the exchange selector ES' and to repeat the busy flash in a connection originating at a manual exchange.
- 50 In order to describe the operation of the automatic to automatic repeater R^1 , Fig. 10, it will be assumed that the subscriber at station A in the automatic exchange No. 1 desires to establish a connection with the subscriber A^3 , in the automatic exchange No. 3. From the trunking layout in Fig. 1 it will be seen that the first three digits representing the exchange name in which the subscriber at A^3 is located will be translated in the director equipment into three series of impulses comprising six, two, and three impulses, respectively.

Assuming that the subscriber at substation A takes into use the director D , dials the first

three digits representing the wanted exchange 65 name and the four digits of the wanted subscriber's number. The director will operate in the same manner as previously described except that it will send out the three series of impulses, six, in the first, two in the 70 second, and three in the third, and then the subscriber's digits two, three, four, and five. Responsive to the first series of impulses sent out by the director the wipers 80-82, inclusive, the exchange selector ES , Fig. 2, 75 will be raised opposite to the sixth level and the switch will then hunt for an idle trunk leading to the exchange selector ES^1 . Assuming the trunk comprising conductors 603 and 604 is taken into use the next series of 80 impulses will set the wipers 627-629, inclusive, of the selector ES^1 , Fig. 9, opposite to the second level of bank contacts and at the end of this series of impulses the switch will hunt for an idle trunk leading to the automatic to automatic repeater R^1 , Fig. 10.

Assuming that the trunk comprising conductors 700-702, inclusive, is the one taken into use, line relay 703 of the repeater R^1 will energize over conductors 700, 702 and the loop circuit extending back to the director D . Line relay 703 upon energizing completes parallel energizing circuits for relays 704 and 707 at armature 712, and at armature 713 connects relay 705 across trunk conductors 95 714 and 715 in series with the right hand winding of the shunt field polarized relay 708.

Relay 707, however, is slightly slow to pull up and does not energize at this time as its circuit is opened at armature 716 of relay 100 705.

Relay 704, upon energizing, earths the release trunk conductor 701 at armature 717 thereby rendering the trunk busy and holding up the switching relay 612 of the exchange 105 selector ES^1 , it being understood, of course, that the release relay 606 of the exchange selector ES^1 is slow to release and maintains the switching relay energized until earth is fed back by the energization of relay 704. 110

Relay 704 at armature 718 completes an energizing circuit for the polarizing winding of the shunt field relay 708, relay 708, however, does not energize at this time on account of the direction of current through its 115 right hand winding opposing that in the left hand winding.

Relay 704 also at armature 719 prepares a circuit for slow relay 706. As previously stated relay 705 is connected across the trunk conductors 714 and 715 in series with the right hand winding of relay 708 upon the energization of line relay 703 whereupon relay 705 and the line relay of the exchange selector ES^4 energize. The line relay of the exchange selector ES^4 prepares the switch for operation in the usual manner and relay 120 705 opens the circuit of relay 707 at armature 125 716.

ture 716 and at armature 726 prepares a circuit for connecting the busy flash conductor 720 to the trunk conductor 700.

Upon the director D sending out the last 5 series of exchange selecting impulses line relay 703 will deenergize three times and these impulses will be repeated over conductors 714 and 715 to the line relay of the exchange selector ES⁵.

Upon the first deenergization of relay 703 10 a circuit is completed at armature 712 over 719 for slow relay 706. Relay 706, upon energizing, opens another point in the circuit of relay 707 at armature 721 and at 15 armature 722 provides a direct loop across conductors 714 and 715 excluding the impedance of relays 705 and 708 from the impulsive circuit, and relay 705 accordingly deenergizes.

At the end of the series of impulses slow 20 relay 706 deenergizes and relay 705 energizes by battery over conductor 714 and earth over conductor 715. Assuming that all the trunks in the third level of the exchange selector 25 ES⁴ to be busy intermittent earth and busy tone will be connected to conductor 714 in the exchange selector ES⁴. This intermittent earth on conductor 714 will intermittently short circuit relay 705 which will intermittently deenergize and energize. Relay 705, 30 upon deenergizing, completes a circuit for slow to pull up relay 707 as follows: earth, armature 712 and its working contact, armature 716 and its resting contact, resting contact and armature 721, normally closed contacts controlled by armature 723, armature 35 724 and its resting contact, relay 707 to battery. Relay 707 upon energizing completes a locking circuit for itself at armature 723 and at armature 725 prepares a circuit for intermittently earthing conductor 700. Each 40 time relay 705 energizes in response to the removal of earth from conductor 714 it earths conductor 700 at armature 726, earth being supplied through the low resistance winding 45 of relay 709 to the common conductor 720.

In the present connection the intermittent earth on conductor 700 will not serve any useful purpose since the call originated in 50 an automatic exchange and the calling subscriber will receive the busy tone in the usual manner. If, however, the call had originated at a manual exchange the intermittent earth would serve to flash an operator's supervisory 55 lamp.

It may be stated here that relays 709, 710, and 711 are common to an exchange and are provided in order to insure that the earth on the common conductor 720 will be removed 60 after a definite time interval determined by the dash-pot relay 711.

Assuming that the exchange selector ES⁴ finds an idle trunk in the third level the remaining four series of subscriber digits will 65 operate the selectors S², S³, and connector

FS', in a similar manner to the operation of the switches S, S¹ and FS. Earth will be fed back from the connector FS' to hold up the switches in the automatic exchange No. 3, and from the repeater R' to hold up the 70 switch or switches in the automatic exchange No. 2, while the exchange selector ES will be held up from the trunk relay group TR. When the wanted party replies the direction of current will be reversed over conductors 714 and 715 whereupon the shunt field polarized relay 708 operates and reverses the direction of current over conductors 700 and 702. This reversal will bring about the operation of relay F in the trunk relay group TR 80 and the calling party's meter M will be operated to register the call.

The release of the connection is under the control of the calling party and when he replaces his receiver relay 25 in the trunk relay 85 group TR will deenergize and open the circuit of relay 27 and relay 703 in the repeater R'. Relay 27 upon deenergizing will bring about the release of the selector ES and relay 703 upon deenergizing will open the circuit 90 of relays 704 and 705 and the line relay in the connector FS³. Relay 704 upon deenergizing will bring about the release of the selector ES' and when the line and release relays in the connector deenergize all switches 95 in the automatic exchange No. 3 will be released.

Interexchange automatic to manual through an automatic to manual repeater.

In order to explain the feature of the invention concerning the automatic to manual repeater a description of a connection from the subscriber at substation A⁴ in the automatic exchange No. 2 to the toll operator in 105 the manual exchange No. 4 will now be given.

Assuming the subscriber at substation A⁴ in the automatic exchange No. 2, Fig. 1, removes his receiver and seizes the line switch LS' which in turn seizes the trunk relay 110 group TR' and its associated selector ES³, and the secondary line switch SLS¹ seizes the director selector DS' which in turn seizes the director D'.

The line switch LS', the trunk group TR' 115 exchange selector ES³, secondary line switch SLS¹, the director selector DS' and the director D' are identical with the corresponding apparatus in the automatic exchange No. 1 and it is not thought necessary to again describe these apparatus in detail.

When the calling party dials the number of the toll exchange operator which is TOL these digits will be recorded in the director in the manner previously described. The recorded digits will be translated in the director into a code of two series of impulses, comprising two impulses in each series in order to route the call through the automatic exchange No. 3. This is brought about by con- 130

necting both terminals 1 and 2 on the right hand side of the IDF to terminal 2 on the left hand side and terminal 3 on the right hand side to the switching through terminal 5 ST on the left hand side. When the sender control switch SCS advances to third position after controlling the transmission of the two series of impulses to route the call to the wanted exchange, earth will be connected to 10 terminal ST whereupon relay 205 will be energized with the hereinbefore described results.

The first series of impulses will set the 15 wipers of the exchange selector ES³ opposite to the second level of bank contacts and at the termination of this series of impulses the switch ES³ will automatically hunt over the second level for an idle trunk leading to a secondary line switch. Assuming the trunk 20 comprising conductors 800-802, inclusive, and terminating in the secondary line switch SLS³, Fig. 11, is the one taken into use a circuit will be completed for the polarized relay corresponding to the polarized relay 316 25 of the director D, Fig. 4, on account of the reversal of the trunk conductors 800 and 802. Referring to the polarized relay 316 it will be seen that it completes a locking circuit at 30 armature 216 for stop relay 381 independently of relay 378 and consequently the transmission of the next series of impulses is dependent upon the deenergization of the polarized relay 316 and not upon the deenergization of relay 378 which occurs shortly after 35 the sending switch returns to normal after transmitting the first series of exchange selecting impulses. The polarized relay 316 also operates its armature 254 but this has no effect upon relay S as the circuit of the latter was opened by wiper 309 of the master 40 digit switch MDS which is now in an off normal position. When the connection was extended to conductors 800 and 802 the line relay 803 of the secondary switch SLS³, Fig. 45 11 energized in series with the polarized relay 316 of the director, and brings about its trunk selecting operation. The trunk selection takes place in known manner, and when the wipers 805-807, inclusive, are brought 50 into engagement with the bank contacts of an idle trunk line which it will be assumed are the bank contacts in which the interexchange trunk conductors 808 and 809 terminate, the switching relay 804 is energized to extend the trunk conductors 800 and 802 over the interexchange trunk conductors 808 and 809 to 55 the exchange selector ES⁴ in the automatic exchange No. 3. The selector ES⁴ is identical with the selector ES³ and it is therefore not 60 thought necessary to describe its operation in detail.

It will be noted that the trunk conductors 808 and 809 are also reversed and it follows therefore that when the switching relay 804 65 operates that the current through the polar-

ized relay 316 in the director will be reversed back to normal and that the relay 316 will deenergize. Relay 316 upon deenergizing opens the locking circuit for stop relay 381 at armature 316, whereupon the sending switch 70 SEN is started to send out the second series of impulses. It will now be seen that by reversing the incoming and outgoing trunk conductors of the secondary line switch SLS³ that the transmission of impulses by the sending switch SEN is positively held up during the time that the secondary line switch is hunting for an idle trunk. This feature is very useful as it positively prevents wrong 75 connections through the sender starting to 80 send out impulses before the selector ES⁴ is ready to receive them.

The second series of impulses sent out by the director now operates the exchange selector ES⁴, which raises its wipers 810-812, inclusive, opposite to the second level of bank contacts. At the end of this series of impulses the selector ES⁴ automatically hunts for an idle trunk in that level. Assuming that the trunk comprising conductors 813- 85 815, inclusive, and terminating in the automatic to manual repeater R², Fig. 12, is the one taken into use, then a circuit will be completed for relays 816 and 817 being fed through relay 816 and earth through relay 90 817.

Relay 816 upon energizing opens a point in the locking circuit of relay 817 at armature 825 and at armature 826 prepares a circuit for supervisory relay 823 of the operator's 100 cord circuit O'.

Relay 817, upon energizing, completes a circuit for slow release relay 818 at armature 827. Relay 818 upon energizing earths the release trunk conductor 814 at armature 828, 105 thereby rendering the trunk busy and holding up the switching relay of the exchange selector ES⁴ over release trunk conductor 814. Relay 818 also connects a ringing tone current to the incoming trunk conductor 813 from the ringing tone machine RT through the small condenser RTC, at armature 830 in order that the calling party may receive the ringing tone when dialling a manual exchange, and at armature 829 completes the 110 following circuit for the calling relay 820 at the operator's position in the toll exchange, earth, lower winding of relay 819, working contact and armature 829, trunk conductor 830, armature 832 and its resting contact, 115 winding of relay 820 to battery. Relay 820 energizes in this circuit but relay 819 does not energize over its lower winding on account of the high resistance of relay 820.

Relay 820 upon energizing completes a 125 circuit for the calling lamp CL at armature 833.

The toll operator upon seeing the lighted condition of the calling lamp CL inserts the plug P into the jack J, whereupon a circuit 130

is completed for relay 821 over the sleeve of the jack J, sleeve of the plug P, relay 822 to battery. Relays 821 and 822 energize in series, the former opens the circuit of relay 820 whereupon the calling lamp CL is extinguished and the latter prepares a circuit for the supervisory lamp SL' at armature 834. When the plug P was inserted in the jack J the following circuit was also completed for 5 relays 819, 823 and 824; earth, relay 823, tip of plug P, tip of jack J, conductor 831, armature 826 and its working contact, upper winding of relay 819 to battery, and earth, lower winding of relay 819, working contact and armature 829, conductor 830, 10 ring of jack J, ring of plug P, relay 824 to battery.

Relays 819 and 823 energize over this circuit the former disconnects the ringing current tone from conductor 813 at armature 835, and at armature 836 prepares a locking circuit for relay 817, and the latter opens a point in the circuit of the supervisory lamp SL' at armature 837. 15 The connection is now completed to the toll operator who converses with the calling party and completes the connection in known manner. During the conversation the exchange selector ES³, the secondary line switch SLS³, 20 and the relays 816 and 817 of the repeater R² are held up from the trunk relay group TR' while the exchange selector ES³ is held up from the repeater R².

The release of the connection however, is 25 under the control of the toll operator and in order to explain this feature of the invention we will assume that the calling party hangs up his receiver while the plug P is still in the jack J.

When the calling party hangs up his receiver relay 25 in the trunk relay group TR deenergizes and opens the circuit of relay 27 which relay being slow to release does not deenergize at this time. Relay 25 at armature 30 47 opens the circuit of relays 816 and 817 in the repeater R², Fig. 12, connects one side of relay 27 to trunk conductor 815 over the following circuit: relay 27, back contact and armature 47, normally closed contacts controlled by armature 50, normally closed contacts controlled by armature 51, armature 65 and its working contact, wiper 82, lower trunk conductor of the exchange selector ES³, Fig. 11, conductor 802, wiper 805, of the 35 secondary line switch SLS³, Fig. 11, interexchange conductor 808, wiper 812 of the exchange selector ES³, trunk conductor 815, armature 825 and its back contact (relay 816 being now deenergized) working contact and armature 836, resistance 838 to battery. Battery through resistance 838 now holds release 40 relay 27 in the trunk relay group, Fig. 2, and relay 817 in the repeater R² energizes thereby placing the release of the connection under 45 the control of relay 819 which can only de-

energize when the operator removes the plug P from the jack J.

When the relay 816 deenergizes it opens the circuit of relay 823 in the operator's cord circuit at armature 826, whereupon a circuit 50 is completed for the supervisory lamp SL' at armature 837.

Relay 819, however, remains energized over its lower winding in series with relay 824 until the operator removes the plug P 55 from the jack J. With these conditions prevailing a local locking circuit is now completed, for relay 817 as follows: earth, relay 817, armature 825 and its resting contact, working contact and armature 836, resistance 838 to battery. Relay 817 energizes and again completes a circuit for relay 818, which being slow to release is still energized and the release trunk 814 is therefore maintained busy until the toll operator takes down the 60 connection, whereupon all relays now energized in the repeater R², and the toll operator's cord circuit deenergizes.

From the foregoing description it will be readily understood how a subscriber at station A⁴ in the automatic exchange, No. 2, sets up a connection to either the local subscriber A² or to the subscriber A³ in the automatic exchange No. 3.

A connection from the subscriber A⁵ of the 65 manual exchange No. 3 to the subscriber A³ in the automatic exchange No. 3 does not involve the use of director apparatus as will be seen from Fig. 1.

The operator at the "B" board receives 70 calls from a manual exchange and completes the connection over numerical switches.

The connection from subscriber A⁵ to subscriber A³ would be completed by the "B" operator sending four series of impulses comprising nine, three, four, and five impulses which would operate the selectors S⁶, S³ and the connector FS¹.

The apparatus associated with the B operator's position is fully described in the specification of British Patent 220,405.

What is claimed is:

1. In a telephone system, a calling subscriber's line, step-by-step switches for setting up a connection, register senders for controlling said switches, a trunk relay group accessible to said line, means for connecting an idle register sender with said relay group when the same is taken into use, means controlled by said relay group for directing the impulses generated by the subscriber to a register sender in case one is connected up, thereby preventing the impulses from directly operating said switches, means for suppressing said impulses in case the register sender is not connected or is disconnected from said relay group, and means for maintaining the release of the switches under control of the calling subscriber. 120

2. In a multi-office telephone system, a first 125

- selector, switches accessible to said selector, local and inter-office trunk lines accessible to said switches, means for extending a calling line to said selector, means including a register sender for operating the selector and one of the said switches to further extend the calling line to a local or inter-office trunk line, means in said selector for feeding a holding ground forward to the operated one of said switches so that repeaters are not required in the inter-office trunk lines, and means in said register sender for transmitting impulses over the two sides of the connected trunk line in series.
- 15 3. In a telephone system, a first exchange, an intermediate exchange, a distant exchange, automatic switches in the first and intermediate exchanges, said switches including a first selector repeater in said first exchange for feeding talking battery to the calling line, a director in said first exchange, means in said director and controlled thereby for directly operating said switches to establish connections between said first exchange and either 20 of said other exchanges, an impulse repeater in the intermediate exchange, and means for including said impulse repeater in one of said connections only when said connection extends from said first exchange through said 25 intermediate exchange to said distant exchange.
4. In a telephone system, a calling subscriber's line, a trunk circuit, a selector switch associated with said trunk circuit, directors, a relay in said trunk circuit, contacts on said relay for connecting an idle one of said directors with said trunk circuit in response to the initiation of a call by the calling subscriber, and for cutting off said director 30 when no longer required, contacts on said relay for controlling the operation of said selector switch, and contacts on said relay for feeding talking battery to the calling subscriber for talking purposes.
- 45 5. In a telephone system, an automatic switch, a trunk, means including said switch and said trunk in serial relation for setting up a connection, a line relay in said switch, a release relay in said switch, said release 50 relay controlled by said line relay, means controlled by said release relay for releasing said switch, a holding circuit for said release relay including said release relay and one talking conductor of said switch and 55 trunk in series, and means for closing said circuit to render the releasing means inoperative responsive to an attempt to release said switch.
6. In a telephone system, an automatic switch, a trunk, means controlled by a calling subscriber and including said trunk and switch in serial relation for setting up a connection, a release relay normally under control of said subscriber for controlling the release of said switch, means controlled by said 60 subscriber for operating said release relay to release said switch, a holding circuit for said release relay including said release relay, one talking conductor of said trunk and switch in series, and means responsive to an attempted release of said switch by the calling subscriber for closing said circuit to render said releasing means inoperative.
7. In a telephone system, an automatic switch, a trunk, means including said switch and trunk in serial relation for setting up a connection to another subscriber or to an operator, a line relay in said switch, a front and a back contact on said relay, a release relay in said switch, a circuit for said release relay including said front contact, means for energizing said line relay to close said circuit to initially energize said release relay, means for deenergizing said line relay to open said circuit to deenergize said release relay in case another subscriber was called, means controlled by the deenergization of said release relay for releasing said switch, a holding circuit for said release relay including said back contacts, one talking conductor of said switch and said trunk in series, and means responsive to the deenergization of said line relay in an attempt to release the switch if the operator was called for closing said holding circuit to prevent the deenergization of said release relay and the release of said switch.
8. In a telephone system, a calling line, a called line, an automatic switch, a trunk, means controlled by the calling party and including said switch and trunk in serial relation for setting up a connection between the calling and called lines, a release relay normally under control of said calling party for controlling the release of said switch, means controlled by said calling party for operating said relay to release said switch, a holding circuit for said relay including said relay, one talking conductor of said switch and trunk in series, and means controlled by the calling party hanging up his receiver before the called party for closing said holding circuit to render said releasing means ineffective to release said switch.
9. In a telephone system, a first exchange, a second exchange, switches in the said exchanges, a director in the first exchange, loop circuits including the talking conductors of said switches in series for controlling the operation of said switches, each of said loop circuits including conductors extending to and included in said director, and means in said director for directly operating said switches over said loop circuits to establish connections between said exchanges.
10. In a telephone system, a calling line, a trunk relay group accessible to said line, director selectors, means for connecting an idle director selector with said relay group when the same is taken into use, an impulse responding relay in said relay group, an im-

pulse responding relay in said director selector, and means for controlling said impulse relays over a circuit including said relays and calling line in series.

5 11. In a telephone system, a calling line, a trunk relay group accessible to said line, register senders, means for connecting an idle register sender with said relay group when the same is taken into use, an impulse responding relay in said relay group, an impulse responding relay in said register sender, and means for controlling said impulse relays over a circuit including said relays and calling line in series.

15 12. In a telephone system, a calling line, a trunk relay group accessible to said line, a selector switch associated with said relay group for extending a connection, register senders for operating said switch, means for 20 connecting an idle register sender with said relay group when the same is taken into use, a relay in said relay group for controlling the release of said selector switch, a relay in said register sender for controlling the 25 release of said register sender, and means for controlling said relays over a circuit including said relays and calling line in series.

30 13. In a telephone system, a calling line, a line switch for the calling line, a trunk relay group accessible to said line switch, a selector switch associated with said relay group for setting up a connection, a secondary switch associated with said relay group, a director selector accessible to said secondary 35 switch, a register sender accessible to said director selector for controlling said selector switch, means responsive to a call by the calling line for establishing a connection from said calling line through said line switch, relay group, secondary switch, and director selector to said register sender, a relay in said relay group for controlling the release of said line and selector switches, a relay in said register sender for controlling 40 the release of said register sender, director selector, and said secondary switch, and means for controlling said relays over a circuit including said relays and calling line in series.

45 14. In a telephone system, a calling line, a first switch, a second switch, means for connecting said line with both said switches, an impulse responding relay associated with said first switch, a second impulse responding relay associated with said second switch, said first relay connected to one side of said calling line, said second relay connected to the other side of said calling line, and means for energizing said relays in series over the 50 calling line.

55 15. In a telephone system, a calling line, a first switch, a second switch, means for connecting said line with both said switches, an impulse responding relay associated with said first switch, a second impulse responding re-

lay associated with said second switch, said first relay connected to one side of said calling line, said second relay connected to the other side of said calling line, means for energizing said relays in series over the calling 70 line, and means at said second switch for deenergizing said first relay.

16. In a telephone system, a calling line, a first switch, a second switch, means for connecting said line with both said switches, an 75 impulse responding relay associated with said first switch, a second impulse responding relay associated with said second switch, said first relay connected to one side of said calling line, said second relay connected to 80 the other side of said calling line, means for energizing said relays in series over the calling line, and means at said second switch for short circuiting said first relay to cause the same to deenergize.

17. In a telephone system, a calling line, a first switch, a second switch, means for connecting said line with both said switches, an impulse responding relay associated with said first switch, a second impulse responding relay associated with said second switch, said first relay connected to one side of said calling line, said second relay connected to the other side of said calling line, means for energizing said relays in series over the calling 90 line, means for operating said switches, and means responsive in case of failure to operate said switches for short circuiting said first relay at said second switch.

18. In a telephone system, a calling line, a 100 trunk circuit accessible to said line, means for connecting said trunk circuit with said line, a line relay in said trunk circuit energized over the talking conductors of said trunk line and calling line in series, register senders for controlling automatic switches to set up a connection, means for connecting an idle one of said register senders with said trunk circuit, an impulse responding relay in said register sender adapted to be operated by impulses generated by the calling party, and means for energizing said impulse responding relay in series with said line relay.

19. In a telephone system, a calling line, a 115 selector switch accessible to said line for use in establishing a connection, a relay associated with said switch adapted to be controlled over the two sides of the calling line in series, means for grounding one side of the calling line to short circuit said relay, a source of signalling current, and means responsive to said last means for connecting said source to said line.

20. In a telephone system, a calling line, a 125 selector switch accessible to said line for extending a connection, a relay associated with said switch adapted to be controlled over the two sides of the calling line in series, means for grounding one side of the calling line to 130

short circuit said relay, a source of signalling current, and means responsive to said last means for operating said switch a single step to connect said source to said line.

5 21. In a telephone system, a calling line, a selector switch accessible to said line, means for connecting said switch with said line, a line relay in said selector switch, a local bridge for said relay closed responsive to said 10 connection, register senders for controlling the operation of said switch, means for connecting an idle one of said register senders with said selector switch, a second bridge for said relay including contacts in said 15 register sender, and means responsive to the connection of said switch with said register sender for substituting said second bridge for said first bridge.

22. In a telephone system, a calling line, a selector switch accessible to said line, means for connecting said switch with said line, a line relay in said selector switch, a local bridge for said relay closed responsive to said connection, directors for controlling the 25 operation of said selector switch, a director selector for selecting an idle one of idle directors, means for connecting said director selector with said selector switch, a second bridge for said relay including contacts in 30 said director selector, and means for substituting said second bridge for said first bridge.

23. In a telephone system, a calling line, a selector switch accessible to said line, means for connecting said switch with said line, a line relay in said selector switch, a local bridge for said relay closed responsive to said connection, directors for controlling the 35 operation of said selector switch, a director selector for selecting an idle one of idle directors, means for connecting said director selector with said selector switch, a second bridge for said relay including contacts in 40 said director selector, means for substituting said second bridge for said first bridge, means for operating said director selector to select an idle one of said directors, a third bridge for said relay including contacts in 45 said selected director, and means for substituting said third bridge for said second bridge.

24. In a telephone system, a calling subscriber's line, a switch, means for operating said switch in a variable number of steps to 55 extend a connection, said means controlled by said subscriber dialling any desired number, and means dependent upon the subscriber dialling any number after a predetermined delay for operating said switch only 60 a single step regardless of the number dialled.

25. In a telephone system, a calling subscriber's line, a switch, means for operating said switch in a variable number of steps to 65 extend a connection, said means controlled

by said subscriber dialling any desired number, and means dependent upon the subscriber dialling any number after a predetermined delay for operating said switch a fixed number of steps regardless of the number dialled. 70

26. In a telephone system, a calling subscriber's line, a switch, means for operating said switch in a variable number of steps to extend a connection, said means controlled by said subscriber dialling any desired number, means dependent upon the subscriber dialling any number after a predetermined relay for operating said switch only a single step regardless of the number dialled, a source of signalling current, and means dependent upon the operation of said last means for connecting said source to the line of the calling subscriber. 80

27. In a telephone system, a calling subscriber's line, a switch, means for operating said switch in a variable number of steps to extend a connection, said means controlled by said subscriber dialling any desired number, means dependent upon the subscriber dialling any number after a predetermined delay for operating said switch a fixed number of steps regardless of the number dialled, a source of signalling current, and means dependent upon the operation of said last means for connecting said source to the line of the calling subscriber. 90

28. In a telephone system, a calling subscriber's line, a switch accessible to said line, a magnet for operating said switch, a circuit for said magnet, means for operating said magnet over said circuit to operate said switch a plurality of steps to extend a connection, said means controlled by the calling subscriber dialling any desired number, means dependent upon the subscriber dialling any number after a predetermined delay for sending a single impulse over said circuit to said magnet to operate said switch a single step, and means operated thereafter for opening the circuit to said magnet and for suppressing the remaining impulses of said number. 100 105 110

29. In a telephone system, a calling line, a trunk circuit, a call director, means for extending a connection from said line to said 115 trunk circuit, means for thereupon connecting said trunk circuit with said director whereby the desired number may be received and retransmitted, a selector switch, a stepping magnet therefor, said magnet having a circuit, a timing device, means controlled by said device for disconnecting said director from said trunk circuit, and means responsive to the calling subscriber dialling after said disconnection for transmitting a single 120 impulse over said circuit to operate said magnet to move said switch one step and for thereafter opening said magnet circuit so as to remove said selector from under control of 125 said line. 130

30. In a telephone system, a calling line, a trunk circuit, a call director, means for extending a connection from said line to said trunk circuit, means for thereupon connecting said trunk circuit with said director whereby the desired number may be received and retransmitted, a selector switch, a stepping magnet therefor, said magnet having a circuit, a timing device, means controlled by 5 said device for disconnecting said director from said trunk circuit, means responsive to the calling subscriber dialling after said disconnection for transmitting a single impulse over said circuit to operate said magnet to move said switch one step and for thereafter opening said magnet circuit so as to remove said selector from under control of said line, a source of signalling current, and means for connecting said source to said line.
- 20 31. In a telephone system, a calling line, a train of switches accessible to said line for setting up a connection, register senders for receiving the impulses sent over the calling line and for retransmitting the same to said 25 switches for controlling the switches during the setting up of a connection, means for connecting an idle register sender with said line, a number unattainable-tone machine associated with the first switch in said train of 30 switches, means operated after a predetermined time if the calling party fails to dial for disconnecting said register sender from said line, and means responsive to the disconnection of said register sender from said 35 line for connecting said machine to said line to notify the calling subscriber that the desired connection cannot be completed.
32. In a telephone system, a calling line, a trunk circuit accessible to said line, register senders for controlling the operation of 40 automatic switches to extend a connection, a switch associated with said trunk circuit adapted to select an idle one of said register senders, means for extending a connection 45 from said line to said trunk circuit and for causing said switch to hunt for an idle one of said register senders, a visual signal associated with said trunk circuit for indicating abnormal conditions, and means responsive 50 to the calling party dialling during the hunting movement of said switch for stopping the hunting movement and for operating said visual signal.
- 55 33. In a telephone system, a calling line, a trunk circuit accessible to said line, director selectors for selecting a group of directors and for then seizing an idle director in the group, a switch associated with said trunk circuit adapted to select an idle one of said 60 director selectors, means for extending a connection from said line to said trunk circuit and for causing said switch to hunt for an idle one of said director selectors, and means responsive to the calling party dialling during the 65 hunting movement of said switch for
- stopping the hunting movement of said switch.
34. In a telephone system, a calling line, a trunk circuit accessible to said line, director selectors for selecting a group of directors 70 and for then seizing an idle director in the group, a switch associated with said trunk circuit adapted to select an idle one of said director selectors, means for extending a connection from said line to said trunk circuit 75 and for causing said switch to hunt for an idle one of said director selectors, a source of signalling current, and means responsive to the calling party dialling during the hunting movement of said switch for stopping the 80 hunting movement of said switch and for connecting said source to said line.
35. In a telephone system, a calling line, a trunk circuit accessible to said line, director selectors for selecting a group of directors 85 and for then seizing an idle director in the group, a switch associated with said trunk circuit adapted to select an idle one of said director selectors, means for extending a connection from said line to said trunk circuit 90 and for causing said switch to hunt for an idle one of said director selectors, a visual signal associated with said trunk circuit for indicating abnormal conditions, and means responsive to the calling party dialling during 95 the hunting movement of said switch for stopping the hunting movement and for operating said visual signal.
36. In a telephone system, a calling line, a train of switches accessible to said line for 100 setting up a connection, register senders for receiving the impulses generated by the calling line and for retransmitting the same to said switches for controlling the switches during the setting up of a connection, a secondary switch accessible to said line and adapted to connect an idle register sender to said line, means for extending a connection from said line to the first switch in said 105 train of switches and for causing said secondary switch to hunt for an idle one of said register senders, a number unattainable tone machine associated with the first switch of said train of switches, and means responsive to the calling subscriber dialling during the 110 hunting movement of said secondary switch for connecting said machine to the calling line.
37. In a telephone system, a calling line, a trunk circuit accessible to said line, a selector switch associated with said trunk circuit 115 for extending a connection, register senders for controlling the operation of said selector switch, a secondary switch associated with said trunk circuit adapted to select an idle one 120 of said register senders, means for extending a connection from said line to said trunk circuit and for causing said secondary switch to hunt for an idle one of said register senders, and means responsive to the calling party 125 130

dialling during the hunting movement of said secondary switch for operating said selector switch a single step and for thereafter removing said selector from under control 5 of said line.

38. In a telephone system, a calling line, a trunk circuit accessible to said line, a selector switch associated with said trunk circuit for extending a connection, register senders for controlling the operation of said selector switch, a secondary switch associated with said trunk circuit adapted to select an idle one of said register senders, means for extending a connection from said line to said 10 trunk circuit and for causing said secondary switch to hunt for an idle one of said register senders, means responsive to the calling party dialling during the hunting movement of said secondary switch for operating said selector switch a single step and for thereafter removing said selector from under control of 15 said line.

39. In a telephone system, a calling line, a trunk circuit accessible to said line, director 20 selectors for selecting idle directors, a secondary switch associated with said trunk circuit adapted to select an idle one of said director selectors, a selector switch associated with said trunk circuit for extending a connection, means for extending a connection from said line to said trunk circuit and for causing said secondary switch to hunt for an 25 idle one of said director selectors, and means responsive to the calling line dialling during the hunting movement of said secondary switch for operating said selector switch a single step and thereafter removing said selector from under control of 30 said line.

40. In a telephone system, a calling line, a trunk circuit accessible to said line, director 35 selectors for selecting idle directors, a secondary switch associated with said trunk circuit adapted to select an idle one of said director selectors, a selector switch associated with said trunk circuit for extending a connection, means for extending a connection from said line to said trunk circuit and for causing said secondary switch to hunt for an 40 idle one of said director selectors, means responsive to the calling line dialling during the hunting movement of said secondary switch for operating said selector switch a single step and thereafter removing said selector from under control of said line, a source 45 of signalling current, and means responsive to the operation of said selector switch for connecting said source to said line.

41. In a telephone system, a trunk circuit accessible to a calling subscriber, register 50 senders for receiving and retransmitting the impulses generated by the calling subscriber for operating automatic switches to extend a connection to a called subscriber, means for connecting an idle one of said register senders 55 with said trunk circuit when the same is

taken into use, means responsive to the calling subscriber dialling a number which does not correspond to any subscriber's number for releasing said register sender from said trunk circuit before any impulses are retransmitted, a visual signal associated with said trunk circuit for indicating abnormal conditions, and means responsive to the release of said register sender from said trunk circuit for operating said signal. 70

42. In a telephone system, a trunk circuit accessible to a calling subscriber, register senders for receiving and retransmitting the impulses generated by the calling subscriber for operating automatic switches to extend 80 a connection to a called subscriber, means for connecting an idle one of said register senders with said trunk circuit when the same is taken into use, means responsive to the calling subscriber dialling a number which does 85 not correspond to any subscriber's number for releasing said register sender from said trunk circuit before any impulses are retransmitted, a visual signal associated with said trunk circuit for indicating abnormal conditions, a number-unattainable tone associated with said trunk circuit for indicating that the call cannot be completed, and means responsive to the release of said register sender for operating said signal and for 90 connecting said tone to the line of the calling subscriber. 95

43. In a telephone system, a calling and a called line, a train of step-by-step switches for completing a connection between said 100 lines, register senders accessible to said calling line for receiving and retransmitting the impulses generated by the calling subscriber to control said switches in setting up a connection, means for connecting an 105 idle one of said register senders with said calling line, means responsive to the calling subscriber dialling the number of said called subscriber for causing said register senders to operate said switches to connect the calling and called lines, a visual signal associated with the first switch of said train for indicating abnormal conditions, and means for operating said visual signal, first, in case the calling subscriber fails to dial within 110 a predetermined time or fails to dial a complete number, second, in case the calling subscriber dials before an idle register sender is connected with the calling line, and, third, when the called subscriber hangs up his receiver before the calling subscriber. 115

44. In an automatic telephone system, a series of automatic switches for connecting a calling line with another line, a control circuit, impulse sending mechanism for transmitting a plurality of series of impulses over said control circuit to operate said switches in succession, means for reversing the direction of current flow in said control circuit after one of said switches has operated, and 125 130

means responsive to said reversal for causing the sending mechanism to delay transmitting the next series of impulses.

45. In an automatic telephone system, a series of automatic switches for connecting a calling line with another line, a control circuit, impulse sending mechanism for transmitting a plurality of series of impulses over said control circuit to operate said switches in succession, means for automatically starting the sending mechanism after each series is transmitted so as to transmit the next series independent of control from said switches, a non-numerical switch inserted in the switch train between two of said switches, and means responsive to the extension of the connection to said non-numerical switch for rendering the automatic starting means ineffective until the said non-numerical switch has operated to further extend the connection to the next numerical switch.

46. In a telephone system, a series of numerical automatic switches and an intervening non-numerical switch for connecting a calling line with another line, a control circuit, impulse sending mechanism for transmitting a plurality of spaced series of impulses over said control circuit to operate said numerical switches in succession, means for reversing the direction of the current flow in said control circuit only when said non-numerical switch has been seized, and means responsive to said reversal for delaying the transmission of the next series of impulses.

47. In an automatic telephone system, a group of directors for handling calls either to called subscribers or to an operator, said subscribers' lines having numbers each with a plurality of digits while the number for calling an operator comprises only a single digit, a director selector having access to said directors from a plurality of levels, and means in each director controlled in accordance with the level over which said director is seized by said director selector for changing the character of the circuits of said director to extend the connection to either a subscriber or an operator.

48. A telephone system as claimed in claim 47 in which the circuit changes in the directors are controlled by reversals in the sets of conductors used to multiple the said levels together.

49. In an automatic telephone system, a combination director for handling calls to either called subscribers or to an operator, means for seizing said director over two paths, and means dependent upon the path over which said director is seized for changing the circuits of said director in accordance with the kind of call which is to be set up.

50. A telephone system as claimed in claim

49 in which a relay in said director is operated when said director is seized over one path to change the circuit of the director to route the call to an operator.

51. In a telephone system, two different switch trains by means of which connections may be established, means including a register sender for controlling the switches in either train by means of groups of impulses, means in said register sender effective to produce a normal spacing between groups of impulses, and means in said register sender effective only when a particular switch train is being set for increasing the spacing between two groups of impulses.

52. In a telephone system including register senders, a first selector, a talking circuit divided into two sections at said selector by inductive connections, a line relay in said selector connected to the talking circuit on one side of said inductive connections for controlling the release of the preceding switch or switches, and a second line relay in said selector connected to the talking circuit on the other side of said inductive connections for controlling the setting operation of said selector.

53. In a telephone system including register senders, a first selector, a talking circuit divided into two sections at said selector by inductive connections, a line relay in said selector connected to the talking circuit on one side of said inductive connections for controlling the release of the preceding switch or switches, a second line relay in said selector connected to the talking circuit on the other side of said inductive connections for controlling the operation of said selector, means for associating a register sender with said selector, and means in said register sender for controlling said second line relay over a portion of said talking circuit for the purpose set forth.

54. In a telephone system, a trunk line, a line switch for extending a calling line to said trunk line, a line relay individual to said trunk line energized over the calling line for maintaining said line switch operated, a directive switch, means responsive to the seizure of said trunk line for extending a branch connection from said trunk line to said directive switch, and a controlling line relay in said directive switch energized over the said calling line in series with said first line relay.

55. In a telephone system, a trunk line, a line switch for extending a calling line to said trunk line, a line relay individual to said trunk line energized over the calling line for maintaining said line switch operated, a directive switch, means responsive to the seizure of said trunk line for extending a branch connection from said trunk line to said directive switch, a controlling line relay in said directive switch energized over the

said calling line in series with said first line relay, a register sender accessible to said directive switch, and a line relay in said register sender adapted to be substituted for the line relay in said directive switch after the directive switch is operated to seize said register sender.

56. In a multi-office telephone system, step-by-step switches for setting up connections, 10 a register sender for controlling said switches, said sender normally arranged to be used in a system employing three digits in the office designation, and manual switching means in said sender to enable the same 15 to be used in a system employing two-digit office designations.

57. In a multi-office telephone system, step-by-step switches, a register sender for controlling said switches to set up connections 20 to either called subscribers or to an operator and normally arranged to be used in a system employing three digits in the office designation, said subscribers' lines having numbers each with a plurality of digits while the number for calling the operator comprises only 25 a single digit, an office register in said sender directly operated responsive to the last two digits dialled in the office designation when a subscriber is called for controlling 30 said switches to route the call to the designated office, separate means independent of said office register for controlling said switches to route the call to the office in which the operator is located when the operator is called, manual switching means in said register sender to enable the same to be used in a 35 system employing two-digit office designations, and means for directly and automatically operating said office register when the operator is called in a system using two-digit-office designations to control said 40 switches to route the call to the operator.

58. In a multi-office telephone system, step-by-step switches, a register sender for controlling 45 said switches to set up connections to either called subscribers or to an operator and normally arranged to be used in a system employing three digits in the office designation, said subscribers' lines having numbers each with a plurality of digits while the number 50 for calling the operator comprised only a single digit, manual switching means in said sender to enable the same to be used in a system employing two digit office designations, an office register in said sender used in 55 either system, and directly operated by the last two digits in the called office designation for controlling said switches to route the call to the designated office when a subscriber is called, and means for operating 60 said office register responsive to calling the operator only in case said switching means has been operated to change said sender to work in a two-digit office designation system.

59. In a telephone system, a selective switch 65 having a directive primary movement and an automatic secondary movement, a normally quick acting changeover relay in said switch energized during the directive movement and deenergized thereafter to start the automatic 70 secondary movement, means for energizing said relay on the first directive movement of said switch, and means operative responsive to the movement of said switch and the operation of said relay for rendering said relay 75 slow to release during the directive movement of said switch.

60. In a telephone system, a selective switch having a directive movement followed by an automatic hunting movement, a normally 80 quick acting relay in said switch energized during the directive movement and deenergized thereafter to start the automatic hunting movement, a magnet for operating said switch in its directive movement, said magnet 85 and said relay connected in multiple, means for sending impulses to said relay and said magnet to cause the directive movement of said switch, and means operative responsive to the operation of said switch and said 90 relay for rendering said relay slow to release during impulsing.

61. In a telephone system, a selective switch having a directive movement followed by an automatic hunting movement, a normally 95 quick acting relay in said switch energized during the directive movement and deenergized thereafter to start the automatic hunting movement, a magnet for operating said switch in its directive movement, said magnet 100 and said relay connected in multiple, means for sending impulses to said relay and said magnet to cause the directive movement of said switch, a stepping relay in said switch, means responsive to the operation of said switch and said changeover relay for energizing said stepping relay, and contacts on said stepping relay for rendering said changeover relay slow to deenergize.

62. In a telephone system, a step-by-step switch having a directly controlled primary movement and an automatic secondary movement, a primary magnet for operating said switch in its primary movement, a secondary magnet for operating said switch in its 115 secondary movement, a quick acting relay connected in multiple with said primary magnet, means responsive to a series of impulses for operating said relay and said primary magnet to operate said switch step-by-step in its primary movement, a stepping relay in said switch for controlling the operation of said secondary magnet, an energizing circuit for said stepping relay including contacts on said quick acting relay, said contact closed responsive to the operation of said switch, contacts on said stepping relay for rendering said quick acting relay slow to release during the sending 120 125

of said series of impulses, and an energizing circuit for said secondary magnet including contacts on both said relays.

63. In a telephone system, a selective switch having a directive controlled primary movement and an automatic secondary movement, a changeover relay in said switch for controlling the changeover from the primary to the secondary movements of said switch, means for making said relay slow acting only during the primary movement of said switch, a source of busy signaling current, and means controlled by said relay for intermittently connecting said source to a talking conductor of said switch whenever said switch over runs its bank contacts in its automatic secondary movement.
64. In a telephone system, a selective switch having a directive primary movement to select a group of trunk lines and an automatic secondary movement to select an idle trunk line in the selected group, a quick acting relay in said switch, means for operating said relay as a changeover relay by energizing said relay at the start of said primary movement and for deenergizing said relay to start the automatic secondary movement, and means for operating said relay as a busy signalling relay by intermittently operating said relay to intermittently connect a source of busy signalling current to a talking conductor of said switch whenever said switch over runs its banks in its automatic secondary movement.
65. In a telephone system, a selective switch having a directive controlled movement to select a group of trunk lines and an automatic movement to select an idle line in the selected group, a quick acting changeover relay energized during the directive movement and de-energized thereafter to start the automatic movement, a stepping relay in said switch for controlling the automatic movement of said switch, means for energizing said stepping relay responsive to the operation of said switch, contacts on said stepping relay for rendering said changeover relay slow to release during the directive movement, means including said stepping relay for operating said switch in its automatic movement to cause said switch to over run its bank contacts

in case all the trunk lines in the selected group are busy, cam springs in said switch, means for operating said springs whenever said switch over runs its banks, a source of busy signaling current, and means for intermittently operating said changeover relay to intermittently connect said source to a talking conductor of said switch responsive to the operation of said cam springs.

66. In a multi-office telephone system, a first exchange, an intermediate exchange, a third exchange, automatic switches in said exchanges, impulse repeaters in said exchanges, means including an impulse sender in the first exchange but excluding said impulse repeaters for directly operating the switches in the first and intermediate exchanges to extend a connection, and means for including only one of said impulse repeaters in case the connection is to be extended to said third exchange to complete the connection, said impulse repeater being included in the connection between the switches of said intermediate exchange and the switches in the third exchange.

67. In a multi-office telephone system, a mechanical tandem office, an automatic office, an intermediate automatic office, and other offices, office selectors having a directive controlled primary movement in said mechanical tandem and automatic offices, two groups of office selectors in said intermediate automatic office, means for routing calls from said mechanical tandem office to one of said groups of office selectors in said intermediate office responsive to a predetermined number of directive steps taken by said office selectors in said mechanical tandem office, means for routing calls from said automatic office to the other of said groups of office selectors in the intermediate office responsive to a different predetermined number of directive steps taken by said office selectors in the automatic office, and multiple connections between the two groups of office selectors in the intermediate office whereby such office selectors have access to local lines or to said other offices via the same trunk lines.

Signed by me at Liverpool, England, this 24 day of November, 1924.

JOHN E. OSTLINE.
